UNITED STATES PATENT OFFICE.

EDMUND C. MORGAN, OF CHICAGO, ILLINOIS.

MINING-MACHINE.

1,325,031.

Specification of Letters Patent. Patented Dec. 16, 1919.

Application filed July 3, 1914, Serial No. 848,727. Renewed July 8, 1919. Serial No. 309,468.

To all whom it may concern:

Be it known that I, EDMUND C. MORGAN, a citizen of the United States, residing at Chicago, in the county of Cook and State of Illinois, have invented certain new and useful Improvements in Mining-Machines, of which the following is a specification.

My invention relates to mining machines, and one of its objects is the provision of improved apparatus for cutting out sections from the mine wall, breaking up such sections into smaller sections and removing the same away from the mine wall for loading purposes.

Another object of my invention is the provision of means for cutting a kerf or kerfs in the mine wall and automatically removing the fine particles of material produced during the kerf cutting operation.

A further object of the invention is the provision of automatic mining apparatus in which a chain cutter cuts out a crescent-shaped section of material from the mine wall, and such section is broken up into smaller sections and moved onto a platform without undue friction and into position where a flight conveyer removes such smaller sections to the rear end of the mining machine in convenient position for loading into mine cars.

Other objects of the invention will appear hereinafter, the novel features and combinations of elements being set forth in the appended claims.

Referring to the accompanying drawings, Figure 1 represents a plan view of my improved mining machine in operative position in a mine; and Fig. 2 is an elevational view, partly in section, of the construction shown in Fig. 1.

The mining machine shown in the drawings comprises a main frame 3, and a supplemental frame 4 which is pivoted to the main frame at 5 between the vertical standards 6. The main frame 3 may be mounted on the skids 7, 7 on the mine floor and may be made of such weight, strength and material as will be suitable. The main frame is also provided with suitable jacks 8, 8, which are mounted at the upper ends to the standards 6. By means of these jacks the main frame may be firmly anchored in adjusted position in the mine, particularly to resist

swinging of the main frame or rearward movement thereof.

The supplemental frame 4 comprises upper horizontally extending bracket arms and a lower horizontally extending platform, which serve to support the various parts of the automatic mechanism. A motor, preferably an electric motor, and shown diagrammatically at 9 in Fig. 1, is mounted on the rear end of the platform to one side thereof. The pinion 11 on the shaft of the electric motor 9 meshes with the gear 12 which is keyed to the transverse shaft 13, the ends of which are mounted in the bearings 14, 14 at the upper rear portion of the supplemental frame 4. At the central portion of the shaft 13 is a worm 15 meshing with the horizontal worm gear 16, below which is a sprocket 17 meshing with the sprocket chain 18. This sprocket chain is provided with a plurality of laterally-extending flights 19, 19, which move over the upper surface of the platform 10. The sprocket chain flight conveyer 18, 19, is endless and its forward portion meshes with a sprocket wheel 20 mounted on a vertical shaft between the platform 10 and the lower end of the forward intermediate connecting frame 21, the upper end of which is connected by means of the stationary bearing 22 to the forward ends of the horizontal bracket arm 23 and 24. These bracket arms 23 extend forwardly from the cross-piece 25 of the supplemental frame and join at their outer ends where the bearing 22 is located.

Mounted on the shaft of the sprocket wheel 20 so as to rotate therewith is a pinion 26, which meshes with a gear wheel 27, mounted in the intermediate frame 21 and provided with a worm 28 meshing with the worm wheel 29. The shaft 30 of the worm wheel 29 is also mounted in the intermediate frame 21 and carries a sprocket wheel 31, as shown in Fig. 1. It should be observed that Fig. 2 shows certain portions of the machine in side elevation when the machine is in the position shown in Fig. 1, and that other parts are shown in end elevation. However, Fig. 2 shows all the parts in side elevation when the chain cutter extends forward in central position.

Meshing with the sprocket wheel 31 is a sprocket chain 32 extending around the

frame 33, which is provided with suitable guideways for said sprocket chain and is supported by the intermediate frame 21. The sprocket chain 32 is provided with cutters 34, extending laterally or axially relative to the cutter frame 33, as shown in Fig. 1. The sprocket chain 32 may be tightened or loosened by means of the nuts 35 and 36, which are threaded on the screw-threaded rod 37 extending rearwardly from the central portion of the chain cutter frame 33. It should be observed, however, that the screw threaded rod 37 is fixed to the rectangular block which extends from and is rigid with the frame 21. This block is provided with guide grooves along its upper and lower surfaces to receive the horizontal spaced-apart bars at the rear portion of the cutter frame 33. Through the vertical cross-piece at the rear end of the bar extends the screw-threaded rod 37, so that when the nut 35 is loosened and the nut 36 tightened, the cutter frame will be moved to the left, either to make more slack in the chain or to permit the radial length of the cutter to be appreciably changed. If necessary a link may be removed in order to prevent the chain from becoming too slack when the desired change in the radial length or range of the cutter is obtained. By loosening the nut 36 and tightening the nut 35 the cutter frame may be moved outwardly relatively to the upright axis of rotation and thus slack may be taken out of the chain or the radial cutting range increased. If desired an extra link may be inserted in order to secure the proper increase in the cutting range without causing the chain to become too tight. After the desired adjustments have been made and one or more links inserted or withdrawn, the nuts 35 and 36 are both tightened to hold the cutter frame firmly in adjusted position relatively to the axial frame 21.

In order to control the operation of the chain cutter I have provided a clutch 38, which may be of any suitable or well known construction, provided with a groove 39 to be engaged by an operating lever. When the current to the electric motor 9 is turned on in the proper direction, motion will be transmitted to the transverse shaft 13 and thence through the worm 15 and worm gear 16 to the vertical shaft 40, the upper end of which is journaled in the bearing 41 at the rear end of the horizontal bracket arm 42 attached to the cross-piece 25 of the supplemental frame. The rotation of the vertical shaft 40 imparts motion to the sprocket 17, which in turn actuates the endless flight conveyor 18, 19 and imparts motion to the sprocket wheel 20, the pinion 26, the gear 27, the worm 28, the worm wheel 29, the sprocket wheel 31 and the chain cutter 32. The arrow 43 indicates the direction of movement of the flight conveyor, and the

arrow 44 indicates the direction of movement of the chain cutter.

The entire chain cutter is also advanced laterally over approximately a semi-circular path during the cutting operation. The means for advancing the cutter chain laterally comprises a peripherally grooved wheel 45 connected to the upper end of the intermediate frame 21, so as to rotate therewith on the bearing 22 and on the bearing in the platform 10 provided for the sprocket wheel 20. To the wheel 45 at 46 is secured one end of a rope 47, the other end of which is secured to a grooved wheel 48, mounted on a vertical shaft carrying the worm wheel 49. It should be observed, however, that the worm wheel 49 is mounted loosely on the shaft 50 and that a clutch 51 is provided for connecting the worm wheel 49 to the wheel 48 so as to transmit motion to the latter from the shaft 50. This may be done by suitable means engaging the groove 52 of the movable member of the clutch 51 in a well known manner. The upper end of the shaft 50 is journaled in the rear end of the bracket arm 23, and the lower end of the shaft 50 is journaled in the bracket arm 53 extending from a portion of the supplemental frame.

Meshing with the worm wheel 49 is a worm 54 on the transverse shaft 13. Therefore, when the electric motor 9 is operated in the proper direction, motion will be transmitted to the worm gear 49 so as to rotate the same in anti-clockwise direction. When the clutch 51 is thrown in, motion will be transmitted through the wheel 48, the rope 47, and the wheel 45 to the intermediate frame 21, thereby swinging the cutter frame laterally from right to left looking forward or in an anti-clockwise direction when viewed in plan. Although I have shown a jaw clutch 51, any other suitable and well known clutch may be used if desired. The same is true with respect to the other clutches shown.

When the cutter frame is in initial position, it is diametrically opposite the position shown in full lines in Fig. 1. The chain cutter loops the section of material in which the kerfs are cut, and when the chain cutter is in substantially central position the shape of the section being cut out will be in cross-section as indicated by the dotted lines 55 in Fig. 2. When a complete semi-circle is made the complete section of material cut out will be crescent shaped in plan view as shown in Fig. 1. Inasmuch as this entire section of material cut out is too large for the conveyor to handle, it is desirable to break up the same into smaller sections. In order to accomplish this result, I provide automatic locking mechanism for holding the cutter frame in its final position and connect to the cutter frame mechanism to exert

a bending force on the crescent-shaped section at one end thereof to break up the same into smaller sections as indicated by the irregular dotted lines 56, 57, 58. In order to lock the cutter frame against being retracted, I provide on the upper surface of the wheel 45 a catch 59, which presents a vertical face toward the cutter frame and an inclined face in the opposite direction. Between the outer ends of the bracket arm 23 and 24 is pivoted a latch lever 60, which will be lifted by the inclined surface of the catch 59 when the wheel 45 approaches the position shown in full lines in Fig. 1. The latch bar 60 being pivoted to the supplemental frame at 61, is free to drop of its own weight when the catch 59 passes under and beyond the same. The vertical face of the catch 59 will then engage the latch bar 60 and prevent the cutter frame from being retracted if it is attempted to do so. In some instances it may be desirable to continue the lateral advancing movement of the cutter frame, and it is therefore preferred to provide an additional catch 62 on the upper surface of the wheel 45, so that the cutter frame may be locked by the catch 62 engaging the latch bar 60. The latch 62 is also provided with an inclined surface over that portion which is visible in plan view. Therefore, when the wheel 45 rotates a sufficient distance anti-clockwise the catches 59 and 62 will lift the latch bar 60, but when it is attempted to rotate the wheel 45 in a clockwise direction, the latch bar 60 coacting with either the latch 62 or the catch 59 will act as a locking mechanism to prevent such return movement. The locking mechanism may be released, however, by lifting manually the latch bar 60 a sufficient distance.

A flat rope or metal belt 64 is connected pivotally at 63 to the front end of the cutter frame 33 opposite the cutters 34. This rope or belt extends around the crescent-shaped section of material cut out and thence toward the rear where it is secured to the drum 65 mounted on the shaft 66, bearings for which are provided on the platform 10 and in the cross piece 25. Loosely mounted on the vertical shaft 66 is a worm wheel 67, which meshes with the worm 68 on the transverse driving shaft 13. When the electric motor 9 is operated, motion will be transmitted to the worm wheel 67 to rotate the same in an anti-clockwise direction. When the clutch 69 is thrown in, motion will be transmitted to the vertical shaft 66 and the drum 65 to exert a pulling force on the belt 64. Now when the locking mechanism comprising the latch bar 60 and the catch 59 is in locking position, the cutter frame 33 will not be retracted when such pull is exerted on the belt 64. The belt will be moved toward the dotted line position thereof

shown in Fig. 1, and in doing so a bending force is exerted on substantially one-half of the crescent-shaped section of material, with the effect of breaking up the same into smaller sections as indicated by the irregular dotted lines 56, 57 and 58. It should also be observed that as the material is broken up into smaller sections it is moved wholly or partially over onto the forward arcuate end of the platform 10. The forward edge of the platform is indicated by the full line 70 in Fig. 1.

Extending radially from the intermediate frame 21 are the arms 71, which constitute a spider having the intermediate frame 21 as its hub. The outer ends of the arms 71 each carry vertical shafts, to the upper and lower ends of which are connected the rollers 72, 72. These rollers are provided with flanges 73, 73, and hold between them a cylinder 74, which is free to rotate on the rollers 72. When the belt or rope 64 is pulled while the cutter frame 33 is held stationary the forward central portion of the spider frame acts as a fulcrum to secure the necessary bending force for breaking up the crescent-shaped section of material into smaller sections. It will be observed that the spider arms 71 may be so located or arranged with respect to the cutter frame that when the latter is locked in position one of the radial arms 71 will project directly forward as shown in Fig. 1. However, the cylindrical drum 74 may itself be made of sufficient strength to act as a fulcrum on which to break up the crescent-shaped section into smaller sections.

In order to move the material onto the platform into such position that the conveyor flights 19 will move the material toward the rear, the lever 60 is lifted after substantially half of the crescent-shaped material has been wrapped around the drum 74, as shown in Fig. 1. When the locking mechanism is released by the lifting of the lever 60 and the rotation of the drum 65 continued, the cutter frame 33 will be gradually pulled around to initial position. As this occurs the cylindrical drum 74 will be free to rotate and therefore its rotation will not be dependent upon the rate of return movement of the cutter frame. The smaller sections of material will be held in contact with the peripheral portion of the drum 74 and move with the same, it not being required for the material to slide over the same while being pressed against it. While the cutter frame is being retracted, the other half of the crescent-shaped section will also be broken up into smaller sections and then advanced toward the flat conveyor, where such sections will drop into the trough 75 and be moved by the laterally projecting flights 19 toward the rear of the platform. A guide plate 76 may be pro-

vided in suitable position to direct the material away from the drum 74, and into proper position with respect to the flight conveyer.

6 In practice I prefer to design and operate the machine in such a manner that two sections of crescent-shaped material between the roof and the floor of the mine will be sufficient before the machine must be moved 10 forwardly to a new position. I prefer also to slice out the upper section first, in order that the bottom of the horizontal kerf may act as a shelf for the fine particles of coal produced by the cutters. When these cuttings are ejected the forward lips 70 of the platform should be in position to receive the same. The chain being operated in the direction of the arrow 44, will cause the cuttings to be moved over the inclined surface 20 77 onto the platform from which they can be readily scraped into the trough 75 to be acted upon by the conveyer flights 19.

It should be observed that the forward lip 70 is adjustable longitudinally because it 25 in reality forms a part of a supplemental platform 10', fitting in suitable grooves or guideways in the main platform 10. By means of a lever 78, pivoted to the supplemental frame at 79 and having a pin-and-slot connection 80 to the supplemental platform 10' the latter may be moved forwardly or backwardly at will. In this manner the position of the lip 70 may be adjusted with respect to the mine wall and the lower horizontal kerf.

In order to adjust the cutter frame to the proper inclination for making a loop cut across the mine wall I provide mechanism for lifting and lowering the supplemental frame. At one side of the main frame and connected rigidly to one of the vertical standards 6 is a forwardly-extending bracket 81, the forward end of which is provided with an opening through which 40 45 extends a screw-threaded rod 82, the lower end of which is pivoted at 83 to a bracket fixed to the platform 10 and extending laterally therefrom as indicated at 84.

Now by turning the wheel 85 which is 50 screw-threaded onto the rod 82, the supplemental frame may be tilted on the pivots 5 and the cutter frame can therefore evidently be moved into position for making a loop cut across the upper portion of the 55 mine wall, or into position for making a loop cut across the lower portion of the mine wall.

In order to shorten the width of the mining machine and enable the same to pass 60 through narrower entries, the supplemental platform 10' may have a section thereof, such as that indicated by the reference character 10" provided with hinges 86, 86, which will enable the section 10" to be folded up- 65 wardly and over against the cylinder 74,

In the operation of the machine, the cutter frame is adjusted to its proper inclination for the production of a loop cut across the mine wall, this being effected by the operation of the wheel 85. Before the cutting 70 operation is begun the cutter frame 33 should be extended diametrically opposite to the position shown in Fig. 1. When the cutter frame is in initial position the entire machine may be moved forward into 75 its new position and held in such adjusted position by means of the jacks 8, 8. During the normal operation of the machine, the cutter frame 33 will be in initial position at the time when the cutter frame is to be 80 readjusted vertically or both vertically and forwardly. Inasmuch as the cutter frame 33 may have sufficient width to act as a shelf or carrier for the material cut out it will hold up its end of the cutout material 85 until ready to be broken into smaller sections and moved onto the platform 10'. If any material remains on the inner lower surface of the cutter frame 33, it will be forced off the same and onto the platform 90 10' inside of the belt 64 as soon as a new cut is begun. When the machine is in readiness for the cutting to begin, the clutch 38 is thrown in to effect the operation of a flight conveyer and of the gears 26, 27, 28 95 and 29 to effect the rotation of the sprocket wheel 31 and the chain cutter 32 in the direction of the arrow 44. At the same time or immediately thereafter, the clutch 51 is thrown in to effect a pull on the rope 47 100 and the gradual feeding forward of the cutter frame through an arc of about 180 degrees. When the cutter frame reaches its limiting position it will be automatically locked against retraction by the latch mechanism comprising the lever 60.

An entire crescent-shaped loop cut having been made across the mine wall, the clutch 51 is thrown out and the clutch 69 thrown in. The pull on the belt 64 will then be exerted 110 to break up into smaller pieces the section just cut away from the mine wall. In doing this the smaller sections of material will be moved partially or wholly onto the platform 10' and wrapped around the drum 74. 115 When this occurs, the lever 60 is lifted to release the latch mechanism, whereupon the pull on the belt 64 will start the cutter frame 33 on its return path to restore the same to initial position. During the retraction of 120 the cutter frame 33 the remaining portion of the crescent-shaped section of material will be broken into smaller pieces and substantially all of the material will be carried into position to be acted upon by the 125 flights 19.

During the retraction of the cutter frame the spider frame with the cylindrical drum 74 thereon will also be rotated in a clockwise direction. If there should be any tendency 130

for the material to slip on the periphery of the drum 74 while being pressed against it, the drum 74 will be free to rotate independently of the spider and the cutter frame, 5 and therefore resistance against movement of the material toward the conveyer will be avoided.

By making a crescent-shaped sectional cut at the upper portion of the mine wall first 10 and then a similar cut immediately below the same, advantage may be taken of the lower surface of the horizontal kerf as a ledge or shelf from which the cuttings may be scraped by the chain onto the platform 15 10' from which they may be moved by the belt 64 and the flight conveyer 18, 19. Whenever desired, the forward lip 70 of the supplemental platform 10' may be adjusted in position by operating the lever 78.

20 By providing an additional notch 87 inclined on its upper surface and having a vertical face to prevent retraction of the cutter frame, and locating this additional catch in the position indicated in Fig. 1, the 25 entire section of blocked-out material may be moved through a short arc. This may be done by releasing the lever 60 from the catch 59 when the clutch 69 is first thrown in to exert a pull on the belt 64. As soon as the 30 lever 60 is released from the latch 59 it may be allowed to engage the catch 87 as soon as the latter has rotated a sufficient distance. The catch 87 will then be relied upon to hold the cutter frame 33 stationary while the pull 35 on the belt 64 continues and while it is being moved toward the dotted line position shown in Fig. 1 to break up the crescent-shaped section into smaller sections.

It should be understood that that portion 40 of the mining machine shown in the drawings as operating in the mine wall may be regarded as the front of the mining machine. The operator may control all the operations from the rear of the mining machine, 45 because devices well known in the art may be provided for operating the lever 78, the wheel 85, the lever 60, and the electric switches for controlling the motor 9, from a suitable location back of the mining machine.

Obviously those skilled in the art may make various changes in the details and arrangement of parts without departing from the spirit and scope of my invention as defined by the claims herein.

By providing the flange at the lower portion of the drum 65 with a series of notches 88, this drum may be held from rotation by the pawl 89, which is pivoted at 90 to the 60 supplemental frame. In this way the drum 65 may be locked against rotation in either direction. When the clutch 69 is released and the pawl 89 moved into one of the notches 88, the drum 65 will be locked while 65 the other end of the belt 64 may continue to

move with the cutter frame. The continued movement of the cutter frame may, therefore, be relied upon, when desired, for breaking up the section cut out even before the same is entirely severed from the mine 70 wall. If the drum 65 is locked at the proper time, the belt 64 will reach the dotted line position when the cutter frame reaches the full line position shown in Fig. 1. It is also contemplated to operate the winding 75 drum 65 to move the belt 64 to its dotted line position while the cutter frame is advancing, thereby breaking up the material by prying it from the mine wall, before any section is entirely severed by the cutting 80 mechanism. These operations of locking the drum and also, when desired, operating the drum while the cutting mechanism is advancing, will increase the efficiency of the apparatus by enabling the cutting mechanism to be restored to initial position sooner 85 after it makes a complete stroke.

It should be noted that the cutter frame when in adjusted position is rigidly connected to the frame 21 which constitutes an 90 upright axle having an upright axis. When the wheel 85 is rotated to tilt the core-cutter on the horizontal axis 5, the vertical axis of swinging movement of the core-cutter will be tilted so as to incline from the lower forward portion upwardly and rearwardly. In this position the core-cutter is enabled to make an arch-shaped cut along the mine roof. This arching of the mine roof is important as it forms a support for the roof and enables the chamber to be cut without the use of props. In this way a self-supporting chamber having an arch-shaped roof which remains intact for a long period of time is produced. This arching of the roof 100 is particularly desirable when there are strata of foreign material in the vein of coal somewhere between the floor and roof of the mine chamber.

Having thus fully disclosed my invention, 110 by describing and illustrating one embodiment thereof, what I claim and desire to secure by Letters Patent of the United States, is:

1. In a mining machine, the combination 115 with a frame, of mechanism having an unobstructed core opening therethrough and mounted on said frame for entirely cutting from a mine wall a crescent-shaped section of material in a general horizontal direction, 120 and automatic means mounted on said frame near said cutting mechanism for effecting mechanically the transfer of the material in its solid state in large blocks from its cut position in the mine wall toward loading 125 position.

2. A mining and loading machine comprising core cutting mechanism for cutting from a mine wall a block of material while retaining the same intact, and means for 130

- moving the severed block of material intact horizontally back from the mine wall between the floor and roof of a mine chamber in a mine and independently of the movement of the machine.
3. A mining and loading machine comprising a supporting frame, a loop chain core cutter mounted on said frame, means for operating said loop chain core cutter to 10 cut a core of material in a mine wall, and automatic means mounted on said frame and extending therefrom into position for acting on the material in its cut position at the mine wall to move it directly away therefrom along said frame toward loading position.
4. A mining and loading machine comprising a supporting frame, a loop chain core cutter mounted thereon, means for operating said cutter to cut a core of material in its native bed, and power mechanism mounted on said frame and extending into position for taking substantially all of the cut material from the place assumed thereby after being cut and moving the same back from the unmined mass along said frame toward loading position.
5. A mining and loading machine comprising kerf-cutting mechanism for cutting from a mine wall a predetermined mass of material, and means operable in a mine chamber between the floor and roof thereof for moving the entire mass of the severed section intact from the upright mine wall 35 in a general horizontal direction along such mine chamber toward loading position.
6. A mining and loading machine comprising a supporting frame, a loop chain core cutter mounted on said frame to extend out from the same, means for operating said cutter to cut a core in a mine wall, and power mechanism mounted on said frame to follow said core cutter in position to act on the material in whatever position it assumes of itself immediately after being cut, to take substantially all of it from such position along said frame toward loading position.
7. A mining and loading machine comprising a supporting frame, a loop chain core cutter mounted thereon and extending out therefrom, means for operating said cutter to cut a core in an upright mine wall, and automatic means mounted on said frame 50 to follow said core cutter and extending out from said frame in position for acting on the mass of the core of material in the mine wall in whatever position it assumes of itself immediately after being cut by said loop chain core cutter, to take substantially all of said material from such position along said frame toward loading position.
8. A mining and loading machine comprising a frame, mechanism mounted thereon for entirely cutting a solid core of material from an upright mine wall while maintaining the core body of substantially the same dimensions as when in its native bed, means for operating said cutting mechanism, power mechanism also mounted on 70 said frame for moving the said solid core of material back from the mine wall in a general horizontal direction between the floor and roof of the mine chamber, and conveyer mechanism connected to said frame for moving said block of material into position for loading.
9. A mining and loading machine comprising a supporting frame, core cutting mechanism having an unobstructed core 80 opening therethrough and mounted on said frame and movable relatively thereto, and dislodging mechanism also movable relatively to said frame for acting on the material in its cut position in the mine wall 85 and moving it directly therefrom toward loading position.
10. A mining and loading machine comprising a supporting frame, mechanism mounted on said frame for cutting a core by 90 cutting on both sides of a body of material in a mine wall and at the back thereof, and manually controlled power mechanism mounted on said frame adjacent said core cutting mechanism for effecting mechanically the transfer of the cut material from its cut position in the mine wall toward loading position independently of the operation of said core cutting mechanism.
11. A mining and loading machine comprising a supporting frame, means for cutting a core of material in its native bed in a mine by cutting on both sides of the core and at the back thereof, conveyer mechanism connected to said frame and movable therewith to be continuously in position for loading the material, and intermediate mechanism mounted on said frame ahead of the receiving portion of the conveyer mechanism and adjacent thereto for effecting mechanically the transfer of the cut material directly from its cut position in a mine wall 105 to said conveyer mechanism.
12. A mining and loading machine comprising a supporting frame, core cutting 115 mechanism mounted on said frame and extending therefrom, means for operating said core cutting mechanism to cut on both sides and at the back of the core in a mine wall, a conveyer mounted on said frame in position 120 for receiving dislodged material, and mechanism mounted on said frame for movement relatively thereto and in position to act on the material substantially in the space originally occupied thereby in its native bed to 125 transfer substantially all of such material over said frame onto said conveyer.
13. A mining and loading machine comprising a supporting frame, mechanism mounted thereon for severing a crescent 130

- shaped section of material from its native bed in a general horizontal direction, means also mounted on said frame in position for moving the severed section bodily away from its severed position while maintaining the material in comparatively large pieces, said means being movable bodily with said frame and always in position for moving cut material away from the unmined mass, and mechanism for operating said moving means to move the cut material relatively to said frame toward loading position.
14. A mining and loading machine comprising a supporting frame, an endless chain cutter, a chain-cutter frame for said cutter and inclosing an open space bounded in front and at the top and bottom by said chain-cutter to guide the latter, means mounted on said frame for operating said chain cutter by actuating the same relatively to said guide frame and moving the latter to feed said chain cutter transversely to the plane of said guide frame to produce kerfs in a mine wall above and below and at the back of a body of material while the latter remains in its native position, means mounted on said frame and extending therefrom for breaking up the material extending through said guide frame, mechanism mounted on said supporting frame for removing the broken up material from the mine wall, and means for swinging the chain-cutter in an upright plane to adjust the same to various heights for a given stationary position of said supporting frame.
15. In a coal mining machine, the combination with a supporting frame, of a chain coal cutter, a cutter frame having a portion for guiding said chain-cutter for producing a plane kerf along said portion, means for driving said chain-cutter to cause the same to travel along said chain-cutter frame, means for feeding said chain-cutter by moving said cutter-frame to cause a core of coal to extend through the same, and means for adjusting the position of the entire chain-cutter frame with the chain-cutter carried thereby, relatively to said supporting frame to vary the path of travel of said chain-cutter for different cuts of coal from the mine wall.
16. In a coal mining machine, the combination with a main frame, of a supplemental frame pivoted to said main frame, an upper chain-cutter carried by said supplemental frame and having upper and lower portions rectilinear in elevation, means for operating said chain-cutter including feeding movement thereof laterally relatively to said supplemental frame during the cutting operation to produce a core having upper and lower flat surfaces along such rectilinear portions of said cutter, and means for adjusting the inclination of said supplemental frame relatively to said main frame to move the chain-cutter including said rectilinear portions to various heights.
17. A mining and loading machine comprising a supporting frame, means mounted thereon for cutting spaced apart kerfs and a back intermediate kerf bounding a core of material in a mine wall, conveyer mechanism mounted on said frame to have a predetermined relation thereto and to said cutting means, and mechanism mounted on said frame intermediate the cutting means and said conveyer mechanism, for taking the dislodged material at various heights directly from the space originally occupied thereby in its native bed, and moving such material onto said conveyer mechanism.
18. In a mining machine, the combination with a supporting frame, of loop chain core-cutting mechanism mounted to swing on an upright axis on the forward portion of said frame, means for operating said core-cutting mechanism including the swinging thereof on said upright axis relatively to the supporting frame while the latter remains stationary, and means for adjusting the elevation of the entire core-cutting mechanism including said upright axis to predetermine the elevation of the core to be cut in a mine wall.
19. A mining and loading machine comprising means for simultaneously cutting spaced apart kerfs, and an additional connecting kerf in an upright mine wall, means for operating said cutting means including the feed thereof across the mine wall to cut a single core of material during each operation, mechanism for adjusting said operating means to cut a core at another elevation during another operation, and means acting on the material in its cut position at various heights for taking the same from its cut position and moving it in a general horizontal direction back from the mine wall toward loading position.
20. In a mining machine, the combination with a loop chain core-cutter having top and bottom runs rectilinear in elevation, said core-cutter having an unobstructed core-opening therethrough, means for operating said loop chain core-cutter including the feed thereof laterally, and means for adjusting the position of the entire chain-cutter including such rectilinear portions to enable successive cuts to be made across the mine wall at various elevations in a coal mine.
21. A mining and loading machine comprising mechanism for cutting spaced apart kerfs and reentrant kerfs extending back of the cut body of material, to cut a core, dislodging mechanism projecting into the reentrant kerfs, means for operating said cutting mechanism to cut a core approximately horizontally across the mine wall, a frame for supporting said core cutting mechanism

and said dislodging mechanism, and means for adjusting the height of said cutting mechanism and said dislodging mechanism relatively to said supporting frame to effect 5 the cutting and dislodgment of cores successively at superposed positions.

22. In a mining machine, the combination with a main supporting frame, of a supplemental frame adjustably mounted on 10 said main frame, core-cutting mechanism mounted on said supplemental frame to swing on an upright axis relatively thereto in feeding direction, means for operating said core-cutting mechanism including 15 swinging movement thereof on such upright axis to cut a core bounded by spaced-apart kerfs, a back connecting kerf and the face of the mine wall adjacent the forward end of said supplemental frame, and means 20 for adjusting the position of said supplemental frame together with said upright axis to vary the elevation of the core-cutting mechanism.

23. In a mining machine, the combination 25 with a main frame, of a supplemental frame adjustably mounted on said main frame, a hub mounted on said supplemental frame having an upright axis of rotation, a cutter-frame extending radially from said hub and 30 having an unobstructed core-opening at its outer portion, an endless loop chain-cutter mounted on said cutter-frame, means for operating said chain-cutter including the feed thereof by lateral movement together 35 with said hub on the upright axis of the latter, and means for adjusting the elevation of said supplemental frame relatively to said main frame to vary the height of 40 said hub together with said cutter-frame and said cutter.

24. In a mining machine, the combination with a supporting frame, of a hub mounted on bearings on said frame, a cutter-frame rigidly connected to said hub and 45 extending radially therefrom and having an unobstructed core-opening at its outer portion, a loop chain core-cutter mounted on said cutter-frame to travel along the same, means for partially rotating said hub together 50 with said cutter-frame to effect feeding of said chain-cutter, means for actuating said chain-cutter to cause the same to travel along said cutter-frame transversely to the direction of the feed thereof, and means for 55 adjusting the elevation of said hub together with said cutter-frame and said chain-cutter.

25. A mining and loading machine capable of alternately cutting and loading 60 cores of material each successively below the preceding core comprising a supporting frame, core-cutting mechanism mounted on said frame, means for operating said core-cutting mechanism, means for adjusting the 65 elevation of said core-cutting mechanism,

and means mounted on said frame for moving the cores back from the mine wall from the path originally occupied in the mine wall by such cores and transferring such cores to loading position while remaining 70 substantially intact.

26. A mining and loading machine comprising mechanism for cutting out from a mine wall a block of material by cutting kerfs simultaneously at the top, bottom and back of such block and leaving it in the space occupied thereby in its native bed, and loading apparatus for effecting the transfer of such block from various elevations at an upright mine wall between the floor and roof 75 of a mine chamber mechanically back from such positions in a general horizontal direction along such chamber toward loading position.

27. In a mining machine, the combination with a main supporting frame, of a supplemental frame, a cutter-frame mounted on said supplemental frame in a substantially vertical plane and having an unobstructed core-opening therethrough, cutter-chain 90 guideways on said cutter-frame including straight top and bottom runs for the chain, an endless loop chain cutter mounted on said cutter-frame to travel along said guideways including said straight top and bottom runs 95 to cut a U-shaped kerf in a mine wall including upper and lower plane kerfs, means for operating said chain-cutter including the actuation thereof along said guideways and the feed of said cutter-frame in a direction transverse to its substantially vertical plane, and means for tilting said supplemental frame to adjust the elevation of said cutter-frame and the chain-cutter thereon.

28. In a mining machine, the combination with a main frame, of a supplemental frame adjustably mounted on said main frame, a hub having end bearing portions mounted on said supplemental frame, a cutter-frame rigidly connected to said hub and extending 110 radially therefrom and having an unobstructed core-opening at its outer portion, a chain-cutter mounted on said cutter-frame and extending from one side thereof, means for operating said chain-cutter including 115 partial rotation of said hub and swinging movement of said cutter-frame to effect the feed of said chain-cutter transversely to the direction of its cutting travel, and means for tilting the supplemental frame together 120 with said hub, cutter-frame and chain-cutter to adjust the elevation of the same.

29. In a mining machine, the combination with a supporting frame, of a hub mounted in bearings on said frame, a cutter-frame 125 connected to said hub to move therewith, an endless chain-cutter mounted on said cutter-frame and extending around an unobstructed core-opening in said cutter-frame, means for operating said chain-cutter in- 130

cluding the feed thereof by partial rotation of said hub relatively to said supporting frame, guides for said chain-cutter on said cutter-frame including a straight run, and means for moving the chain-cutter as a whole in its own plane to adjust it to various cutting positions.

30. In a mining machine, the combination with a supporting frame, of mechanism mounted thereon for cutting cores of material at various elevations across the mine wall each successively below a preceding core, means for operating said mechanism for cutting each core by a single feeding movement across the mine wall, conveyer mechanism mounted on said frame and extending longitudinally thereof, and intermediate mechanism mounted on said frame for dislodging the cut material and moving it onto said conveyer mechanism for transfer toward loading position.

30. In a mining machine, the combination with a supporting frame, of a chain-cutter frame mounted on said supporting frame for arcuate movements relatively thereto, a flexible traveling chain cutter mounted on said cutter-frame, guideways on said cutter-frame for said chain-cutter, said guideways including upper and lower portions for guiding said chain-cutter to produce upper and lower plane kerfs, said cutter-frame having an unobstructed core-opening therethrough for the passage of the core cut by said chain-cutter, means for operating said chain-cutter including actuation thereof along said guideways transverse to the direction of feed and including the swinging of said cutter-frame in an arc on said supporting frame transverse to the path of travel of said chain-cutter along said guideways, and means for adjusting the elevation of said cutter-frame to effect the cutting out successively of a plurality of cores one above the other while the supporting frame remains substantially in the same position.

32. A mining and loading machine comprising core-cutting mechanism having an unobstructed core-opening therethrough, means for operating said core-cutting mechanism to completely detach a single core of material from its native bed in one feeding operation across the mine wall and leaving such core substantially in the space originally occupied thereby, a supporting frame for said core-cutting mechanism, and mechanism mounted on said frame and extending therefrom in position to act directly on the cut material in its position in the mine wall irrespective of its height from the floor of the mine chamber for moving such material toward loading position.

33. A mining and loading machine comprising a supporting frame, means for holding said frame stationary, core-cutting mechanism mounted on said frame for

bodily movement relatively thereto, means for operating said core-cutting mechanism including the feed thereof to completely detach a single core of material from its native bed and leave it substantially in the space originally occupied thereby, conveyer mechanism mounted on said frame in fixed relation thereto and extending longitudinally thereof, and mechanism on said frame intermediate said conveyer mechanism and said core-cutting mechanism for taking the material from the position assumed thereby after being cut irrespective of its height from the mine floor and moving the same onto said conveyer mechanism.

34. A mining and loading machine comprising a supporting frame, a loop chain core cutting having an unobstructed core opening therethrough, and mounted on said frame to extend outwardly therefrom, conveyer mechanism mounted on said frame with its receiving portion spaced back from the outer portion of said core cutter, and intermediate mechanism mounted on said frame to take substantially all the material from the position assumed thereby after being cut by said core cutter, irrespective of the elevation of the cut position of such material above the mine floor, and move such material onto the receiving portion of said conveyer mechanism.

35. In a mining machine, the combination with a main frame, of a supplemental frame mounted for oscillation on a horizontal axis on said main frame, cutting mechanism mounted on said supplemental frame, means mounted on said main frame for swinging said supplemental frame together with said cutting mechanism on said horizontal axis to adjust said cutting mechanism to various heights, means for operating said cutting mechanism including the feed thereof on an upright axis to cut a solid core of material in its native bed, and loading apparatus mounted on said supplemental frame in position relatively to said cutting mechanism for removing the material from the mine wall after being cut by said cutting mechanism.

36. In a mining machine, the combination with a frame having spaced-apart extensions with spaced-apart bearings on the latter, of a hub between said spaced-apart extensions and mounted on said spaced apart bearings, a loop chain core-cutter having an unobstructed core opening therethrough and connected to said hub to move as a whole with said hub, means for operating said chain-cutter including the feed thereof by partial rotation of said hub, and mechanism for effecting adjustment of the height of said hub to vary the height of said core-cutter.

37. A mining and loading machine comprising a supporting frame, a loop chain core cutter comprising an open frame hav-

- ing an unobstructed core receiving opening extending therethrough, said cutter being mounted on said frame for bodily movement therewith, means for operating said loop 5 chain core cutter to cut a solid core of material in an upright mine wall, and means mounted on said frame to operate relatively thereto to act on the cut material to carry the same back from the mine wall directly 10 from the position assumed thereby after being cut, irrespective of the height of such cut material from the floor of the mine chamber.
38. A mining machine comprising loop 15 chain kerf cutting mechanism, a main frame, a supplemental frame on which said cutting mechanism is mounted to swing in feeding direction at right angles to the plane thereof, and means for angularly adjusting 20 the entire cutting mechanism in the plane thereof.
39. In a mining machine, the combination with a main frame, of a supplemental frame, a hub mounted in bearings on said supplemental frame, cutting mechanism having an unobstructed core-opening therethrough and connected to said hub to move bodily therewith in feeding direction, means for operating said core-cutting mechanism including 25 partial rotation of said hub to effect feeding of said cutting mechanism, and mechanism for elevating said supplemental frame to adjust the height of said hub and the height 30 of said cutting mechanism connected to said hub.
40. In mining apparatus, the combination with a frame, of an upright hub mounted in bearings on said frame, a cutter frame connected to said hub to move bodily therewith, said frame having an unobstructed 35 core-opening therethrough, an endless chain-cutter mounted on said cutter-frame and extending laterally therefrom in feeding direction, means for operating said chain-cut- 40 ter by partially rotating said hub to swing said cutter-frame transversely to the direction of cutting travel of said cutter and actuating said chain-cutter to cause it to travel along said cutter-frame, and means 45 for adjusting the height of said hub together with said cutter-frame and said chain-cutter.
41. In mining apparatus, the combination with a main frame, of a supplemental frame 50 pivoted to said main frame on a substantially horizontal axis, an upright hub having end bearing portions connected to said supplemental frame, a cutter-frame connected to the central portion of said hub and 55 extending radially therefrom and having an unobstructed core-opening at its outer portion, an endless chain-cutter mounted on said cutter-frame and extending to an actuating position near the axis of said hub, and means 60 for operating said chain-cutter including feed thereof by partially rotating said hub to swing said cutter-frame arcuately relatively to said supplemental frame, and means for holding the supplemental frame at adjusted elevation relatively to said main 70 frame to predetermine the elevation of the core cut across the mine wall.
42. In a mining machine, the combination with a frame, of a loop chain cutter mounted thereon, means for operating said chain cutter to cut sections of material, means for feeding said chain cutter during the cutting operation substantially at right angles to the plane of said chain cutter, and power mechanism mounted on said frame for 80 breaking up the cut sections of material and moving the same back from the mine wall.
43. A mining and loading machine comprising a supporting frame, core cutting mechanism mounted thereon, and conveyer 85 mechanism mounted on said frame to operate in a plane substantially at right angles to the plane of said cutting mechanism irrespective of the position of said cutting mechanism relatively to said frame or relatively to said conveyer mechanism.
44. A mining and loading machine comprising a supporting frame, a loop chain core cutter mounted on said frame in an upright plane, means for operating said loop 95 chain core cutter including feeding movement thereof relatively to said frame, and conveyer mechanism mounted on said frame to operate approximately in the plane of the lower portion of said loop chain core 100 cutter and in a plane at right angles to the plane of said loop chain core cutter irrespective of the position of the latter relatively to said frame.
45. In a mining machine, the combination with a supporting frame, of core-cutting mechanism mounted thereon and including a guiding frame having an unobstructed core-opening therethrough, and upper and lower runs rectilinear in elevation with the 105 space between them substantially less than the longitudinal length of said cutter-frame projecting forwardly from said supporting frame, means for adjusting the elevation of the forward portion of said cutter frame to predetermine the elevation of the core to be 110 cut from a mine wall between the floor and the roof of a mine chamber, and means for operating said core-cutter in any of its adjusted positions including the feed thereof in a direction transverse to the actuating path to cut upper and lower substantially flat surfaces, and a core projecting through 115 said unobstructed core-opening of said cutter-frame.
46. A mining and loading machine comprising an upright loop chain core-cutter, a frame on which said loop chain core-cutter is mounted while being held in an upright position throughout its range of movement, 120
- 125
- 130

means for operating said loop chain core-cutter, and a conveyer mounted on said frame in a plane transverse to the plane of said loop chain core-cutter, the plane of said 5 conveyer extending through substantially the lowermost length of said loop chain core-cutter.

47. A mining machine comprising a loop chain cutter, a frame for guiding said loop chain cutter, said frame having an unobstructed core opening therethrough, means for feeding said chain cutter transversely to the plane thereof on an axis of rotation, means for actuating said chain cutter, and 15 mechanism for adjusting the radial length of said frame relatively to said axis of rotation.

48. In a mining machine, the combination with a loop chain cutter, of a pivoted 20 frame for supporting and guiding said loop chain cutter, said frame having an unobstructed core opening therethrough, means for swinging said chain and cutter to secure feeding movement of said cutter, means for 25 actuating said cutter during said feeding movement, and means for adjusting the radial length of said frame.

49. A mining and loading machine comprising a supporting frame, of core-cutting 30 mechanism mounted on said frame and having an unobstructed core-opening therethrough, means for operating said core-cutting mechanism including arcuate feed thereof relatively to said frame, and mechanism mounted on said frame to act on the core in the space occupied thereby in its native bed for moving such core directly back from such position along said frame toward loading position.

50. A mining and loading machine comprising a supporting frame, a loop chain core-cutter mounted on said frame, means for operating said core-cutter including feed thereof by swinging it in an arc, and positive means mounted on said frame for acting on the material cut by said cutter and taking it directly from its native position back from the mine wall along said frame into loading position.

51. A mining and loading machine comprising mechanism for cutting a solid core of material in its native bed between the floor and roof of a mine chamber, said cutting mechanism having an unobstructed core 55 opening therethrough, and means movable horizontally back from the mine wall along such chamber to draw the cut material with it for breaking loose such cut material and moving it toward loading position.

52. A mining machine comprising a main supporting frame, core-cutting mechanism mounted thereon for simultaneously cutting spaced-apart kerfs and a back connecting kerf to form a column in a mine wall, means 65 for operating said cutting mechanism in-

cluding the feed thereof to cut such column in a single operation along the mine wall, and means mounted on said frame and movable relatively thereto for breaking off pieces of said column and moving the same 70 toward loading position.

53. In a mining machine, the combination with a supporting frame, of means for holding said frame stationary between the floor and the roof of a mine chamber, a supplemental frame pivotally mounted on said supporting frame, core cutting mechanism mounted at the forward end of said supplemental frame, means for swinging said core cutting mechanism in a general horizontal direction on an upright axis on said supplemental frame, and means mounted on said supplemental frame for acting on the cut material to move the same toward loading 75 position.

54. A mining and loading machine comprising a supporting frame, of a loop chain core-cutter mounted on said frame, means for operating said core-cutter including feeding movement thereof relatively to said 80 frame to cut a core of material in its native bed, and mechanism mounted on said frame and movable relatively thereto to act on the cut material while substantially in its original position in the mine wall to remove the same therefrom in an arcuate path 85 relatively to said frame toward loading position.

55. A mining and loading machine comprising a supporting frame, a loop chain core-cutter comprising a cutter-frame having an unobstructed core-opening therethrough for guiding the chain around the core cut by said cutter, means for operating said cutter including arcuate feed thereof 100 to cut an arcuate core, and means mounted on said frame for moving the cut core of material in an arcuate path away from a mine wall immediately after being cut by said cutter.

56. In a mining machine, the combination with core cutting mechanism, of arcuate feeding means for said core cutting mechanism, and means for removing the cut material along a path concentric with the arcuate 115 feed of said cutting mechanism.

57. A mining and loading machine comprising a supporting frame, means mounted thereon for severing a crescent-shaped block of material in its native bed adjacent said 120 frame, and mechanism mounted on said frame and movable relatively thereto for moving the severed block bodily away from its severed position in an arcuate path of travel immediately after being severed.

58. A mining and loading machine comprising a frame, loop chain core-cutting mechanism mounted on said frame and having an unobstructed core-opening therethrough for the passage of cut material,

means for operating said cutting mechanism including arcuate feed thereof relatively to said frame, and power mechanism mounted on said frame for moving the cut material back from the mine wall relatively to said frame over an arcuate path of travel.

59. In a mining machine, the combination with loop chain cutting mechanism, of means for operating the same to cut a core 10 of material in its native bed, and means for removing the cut material along the line of core cutting feeding movement of said cutting mechanism.

60. In a mining machine, the combination 15 with a supporting frame, of loop chain core cutting mechanism mounted thereon, and power mechanism movable relatively to said supporting frame for removing the cut material along the line of movement of said 20 loop chain cutting mechanism but in reverse direction from such movement.

61. In a mining machine, the combination 25 of kerf cutting mechanism for cutting a core in a mine wall, means for feeding said cutting mechanism on a curved line to entirely sever a block of material, and means for removing said block of material along 30 said curved line.

62. A mining machine comprising core 35 cutting mechanism having an unobstructed core-opening therethrough, means for feeding said cutting mechanism over an arcuate path of travel, and means operating in the kerf produced by said cutting mechanism to move the cut material away from the mine 40 wall independent of the feed of said cutting mechanism.

63. In a mining machine, the combination 45 with a loop chain cutter having an unobstructed core opening therethrough, of means for feeding said loop chain cutter over an arcuate path of travel to sever a crescent-shaped block of material from a mine wall, and means for moving the severed section of material in an arcuate path 50 from the mine wall and moving the said chain cutter to initial position preparatory for another cut.

64. In a mining machine, the combination 55 of means for severing a section of material in its native bed and leaving it substantially in the space occupied thereby, and mechanism for moving the severed material from the mine wall and moving the cutting mechanism to initial position preparatory for another cut.

65. In a mining machine, the combination 60 with a loop chain cutter having an unobstructed core opening therethrough, of means for feeding said loop chain cutter over an arcuate path of travel for entirely severing a crescent-shaped mass of material in its native bed, and means for bodily moving the entire severed mass toward loading 65 position by the restoration of the chain cut-

ter to initial position preparatory for another cut.

66. In a mining machine, the combination with a loop chain core cutter, of means for operating the same, and means for automatically loading the core cut by said cutter by restoring said cutter to initial position preparatory for another cut.

67. A mining and loading machine comprising a supporting frame, cutting mechanism mounted on said frame and adapted to sever a block of material intact in the mine wall, means mounted on said frame for moving said block of material bodily away from the mine wall, mechanism on said 75 frame for coacting with said moving means to break up said block of material into smaller sections, and loading apparatus mounted on said frame to extend rearwardly for moving the smaller sections of material 80 toward loading position.

68. In mining apparatus, the combination with a loop chain cutter having an unobstructed core opening therethrough, of means for operating the same, and power 90 mechanism connected to said loop chain and co-operating therewith to take the material from its cut position toward loading position by acting directly on said material in the position assumed thereby after being 95 cut.

69. In a mining machine, the combination with a loop chain cutter, of a frame guiding the same, means for operating said loop chain cutter to cut a core of material in 100 its native bed, and means connected to said frame for effecting mechanically the transfer of cut material from the mine wall toward loading position.

70. A mining and loading machine comprising a supporting frame, core-cutting mechanism having an unobstructed core-opening therethrough, means for operating said core-cutting mechanism including arcuate feed thereof relatively to said frame, 105 and means mounted on said frame and extending therefrom for breaking the core of material from its native position in a mine wall and moving it toward loading position.

71. A mining and loading machine comprising a supporting frame, a loop chain cutter having an unobstructed core-opening therethrough, means for operating said cutter including the feed thereof to cut a core in a mine wall while remaining integral 110 therewith at one end of such core, and mechanism mounted on said frame to project therefrom back of the core-cutter in position to break off pieces from said core and move such pieces toward loading position.

72. A mining and loading machine comprising a supporting frame, loop chain core-cutting mechanism having an unobstructed core-opening therethrough and mounted on 115

said frame for movement relatively thereto during its feed, dislodging mechanism mounted on said frame for movement relatively thereto, and means for operating said dislodging mechanism to insert the same back of the core cut by said cutting mechanism and move such core away from the mine wall.

73. A mining machine comprising loop chain core cutting mechanism having an unobstructed core-opening therethrough, a supporting frame, and means for intermittently moving successive cores against each other over said frame.

15 74. A mining and loading machine comprising loop chain core cutting mechanism, apparatus capable of being extended into a kerf spaced back from the face of a mine wall at any height between the floor and 20 the roof of the mine chamber, and means for operating said spaced apparatus for moving the material from its cut position in the mine wall toward loading position.

75. A mining and loading machine comprising a supporting frame, loop-chain core-cutting mechanism mounted on said frame for making a U-shaped kerf in a mine wall horizontally across the same, means mounted on said frame and extending therefrom 30 to operate in the said kerf to break down a section severed and pull such section away from the unmined mass, and means on said frame in position to receive the dislodged material and convey it away.

35 76. A mining and loading machine comprising a supporting frame, loop chain core-cutting mechanism mounted thereon for cutting a single core of material in a mine wall and leaving it substantially in the space 40 occupied thereby, and means mounted on said frame and extending therefrom in position for insertion back of the material irrespective of its elevation within predetermined limits to engage such material and 45 move it back from the mine wall.

77. A mining machine comprising mechanism for cutting a plurality of spaced-apart kerfs and an inter-connecting back kerf simultaneously across the mine wall of a mine 50 chamber in a lateral direction, breaking means arranged to follow immediately in the path of said cutting mechanism, a conveyer, and means for adjusting the height of said conveyer to correspond with the 55 height of the laterally movable cutting mechanism, and to the height of said following breaking means.

78. A mining machine comprising cutting means for simultaneously making a plurality of kerfs across the wall of a mine chamber in a general horizontal direction, simultaneously operating breaking means following immediately in the path of the cutting means to break down the section 35 bounded by said kerfs, simultaneously op-

erating loading means comprising a conveyer in position to receive the material dislodged by said breaking means, and moved thereon by the latter, and means for adjusting the elevation of both the cutting 70 means and said conveyer to maintain the same in co-operative relation with said dislodging mechanism for all such elevations.

79. A mining machine comprising cutting means for making a plurality of kerfs simultaneously in a mine wall in a general horizontal direction, simultaneously operating breaking means following immediately in the path of said cutting means to break down the material bounded by said kerfs, simultaneously operating loading means comprising a conveyer in position to receive the material dislodged by said breaking means, and means for adjusting the elevation of said cutting means and said 80 breaking means, and the forward end of said loading means.

80. A mining and loading machine comprising a supporting frame, means mounted thereon in position for cutting a core in a mine wall adjacent said frame, dislodging mechanism mounted on said frame to follow the cutting means to act on the material substantially in the space originally occupied thereby and while resting on the shelf produced by the cutting of such core, and loading apparatus mounted on said frame to extend to such shelf adjacent the bottom of the core to receive the dislodged material directly from its cut position when 100 dislodged from the mine wall.

81. A mining machine comprising a flexible traveling cutter-carrying element, a guide frame therefor having an unobstructed opening therethrough, dislodging mechanism, and means co-operatively related to said dislodging mechanism in close proximity to the lowermost reach of said cutter-carrying element for receiving the dislodged material.

82. In a mining machine; the combination with a supporting frame, of core-cutting mechanism mounted thereon, means for giving said cutting mechanism an arcuate feeding movement on an axis of rotation on 115 said frame, an arcuate fulcrum on said frame spaced from said axis of rotation, and means mounted on said frame to coact with said arcuate fulcrum to break the core of material into smaller sections.

83. A mining and loading machine comprising a supporting frame, core-cutting mechanism mounted on said frame, means for operating said core-cutting mechanism including arcuate feeding movement thereof relatively to said supporting frame, and means mounted on said frame in position to extend in front of and in back of the core cut by said cutting mechanism to co-operate to remove such core from the mine wall.

84. A mining and loading machine comprising a supporting frame, core-cutting mechanism mounted thereon, means for operating said core-cutting mechanism, a flexible device connected to said frame and adapted to extend therefrom to the core cut by said core-cutting mechanism, means also mounted on said frame for moving said flexible device directly against the core of material to break the same away from its native position, and apparatus in position on said supporting frame for receiving the broken material and moving the same toward loading position.
85. In a mining machine, the combination with loop chain core cutting mechanism, of a flexible device connected to said cutting mechanism to enter a kerf produced thereby, and means for exerting a pull on said flexible device to restore said cutting mechanism to initial position.
86. In a mining machine, the combination with cutting mechanism for producing a U-shaped kerf in a mine wall, of a flexible device connected to said cutting mechanism to enter a kerf produced thereby and embrace the cut section of material, and means for exerting a pull on said flexible device to restore said cutting mechanism to initial position.
87. In mining apparatus, the combination with kerf cutting mechanism, of a flexible device connected to the front end thereof, and means for exerting a pull on said flexible device to restore said cutting mechanism to initial position.
88. In mining apparatus, the combination with kerf cutting mechanism, of a flexible device, means for extending said flexible device into the kerf produced by said kerf cutting mechanism to embrace the body of the cut section back of the same, means for holding one end of said flexible device, and mechanism for pulling the other end of said flexible device to dislodge the material from the mine wall.
89. In a mining machine, the combination with a flexible device, of means for moving said flexible device into a kerf in a mine wall back of the body of the material bounded by said kerf, and means for exerting a pull on one end of said flexible device while holding the other end thereof to effect movement of said material back from the mine wall.
90. A mining machine comprising cutting mechanism, means for operating said cutting mechanism, a rotatable drum, and means spaced from said drum but coöperating therewith to break up the material cut out by said cutting mechanism by moving said material directly from its cut position against said drum.
91. A mining machine comprising a supporting frame, core-cutting mechanism mounted thereon, an additional frame mounted on said supporting frame, and means mounted on said supporting frame in position to be spaced from said additional frame to coat with the latter for breaking up the core cut out by said cutting mechanism.
92. A mining machine comprising cutting mechanism, a frame, and means for breaking up the material cut out by said cutting mechanism by forcing said material against said frame directly from the mine wall.
93. A mining machine comprising cutting mechanism, a frame, a cylinder mounted on said frame for movement independently of said frame circumferentially, and means co-operating with said frame and cylinder for breaking up the material cut out by said cutting mechanism by moving the cut material directly from the mine wall against said cylinder.
94. In mining apparatus, the combination with cutting mechanism, of a flexible device connected thereto, a frame, means for locking the cutting mechanism in a predetermined position, and mechanism for exerting a pull on said flexible device to effect the breaking up of said material on said frame.
95. In mining apparatus, the combination with a flexible device, of means for exerting a pull on one end of said flexible device to pull the same into a kerf in a mine wall, and means for exerting a pull on the other end of said flexible device to move material away from the mine wall.
96. In mining apparatus, the combination with a frame, of means for rotating said frame, a flexible device connected to the outer end of said frame, and means for exerting a pull on said flexible device when the same is extended into a kerf in a mine wall.
97. In mining apparatus, the combination with a frame, of an arm, pivoted to said frame, means for swinging said arm, a flexible rope connected to said arm, means for holding said arm in a predetermined position, and mechanism for exerting a pull on said rope when the same is extended into a kerf in a mine wall.
98. In mining apparatus, the combination with a chain cutter, of a drum interlooping said chain cutter, and mechanism coöperating with said drum for breaking up the material cut out by said chain cutter.
99. In mining apparatus, the combination with a chain cutter, of a freely rotatable cylindrical drum interlooping said chain cutter, and mechanism coöperating with said drum for breaking up the material cut out by said chain cutter.
100. In a mining machine, the combination with a supporting frame, of a flexible device movable relatively to said supporting frame to penetrate a mine wall in an arcuate

- path, and means for operating said flexible device to insert the same in a kerf back of the material in a mine wall to engage the same and move it away from the mine wall.
5. 101. A mining and loading machine comprising means for producing a kerf extending in an arc back from the mine wall and spaced therefrom, a belt, and means for inserting said belt in said kerf for engaging the cut material to break it from the unmined mass and move it back therefrom.
102. In mining apparatus, the combination with a swinging arm, of a rope connected to said arm, a platform, a frame, and means for exerting a pull on said rope when the same is extended into a kerf in the mine wall to break up the material by coacting with said frame and moving said material onto said platform.
15. 103. In mining apparatus, the combination with a rope, of means for extending said rope into a kerf in the mine wall, means for exerting a pull on said rope, a conveyer, and mechanism coöperating with said rope to break up cut out material and move the same onto said conveyer.
20. 104. In mining apparatus, the combination with a flexible device, of means for extending said flexible device into a kerf in a mine wall, loading apparatus, means for exerting a pull on said flexible device, and mechanism coöperating with said flexible device to break the material away from the mine wall and move it onto said loading apparatus when the pull on said flexible device is exerted.
25. 105. In a mining machine, the combination with cutting mechanism, of means for operating the same including the feeding thereof, dislodging apparatus comprising a flexible belt connected to said cutting mechanism, and means for locking the cutting mechanism against retrograde movement during the operation of said dislodging apparatus.
30. 106. In a mining machine, the combination with a supporting frame, of a cutter frame mounted thereon, an endless chain core-cutter mounted on said cutter-frame, means for actuating said endless chain core-cutter by causing the same to travel along said cutter-frame, the latter having an unobstructed core-opening therethrough, means for giving said cutter-frame and said core-cutter a swinging movement to feed the latter, dislodging mechanism mounted on said supporting frame and connected to said cutter-frame, means for holding said cutter-frame against return movement, and mechanism for operating said dislodging mechanism while its connection with said cutter-frame is being held against return movement.
35. 107. In a mining machine, the combination with kerf cutting mechanism, of means for operating the same, a belt connected to said kerf cutting mechanism, means for automatically preventing the return movement of said cutting mechanism, and means for exerting a pull on said belt to dislodge cut material.
40. 108. In a mining machine, the combination with a supporting frame, of a supplemental frame movably mounted thereon, a flexible device connected to said supplemental frame to enter a kerf in a mine wall, automatic mechanism for permitting movement of said supplemental frame in said kerf in one direction but preventing movement in the opposite direction, and means for exerting a pull on said flexible device to move material engaged by a portion thereof intermediate its ends.
45. 109. In a mining machine, the combination with a supporting frame, of a supplemental frame movable thereon, means for actuating said supplemental frame, a belt connected to the front end of said supplemental frame to embrace material, means for automatically preventing return movement of said supplemental frame, and means for exerting a pull on said belt to move material engaged thereby.
50. 110. In a mining machine, the combination with a supporting frame, of a supplemental frame adapted to enter a kerf in a mine wall, a belt connected to the front end of said supplemental frame, winding mechanism for the other end of said belt, means for moving said supplemental frame to pull the belt from the winding mechanism, and means on the winding mechanism to hold it from turning when the pull is exerted on said belt by movement of said supplemental frame.
55. 111. In a mining machine, the combination with a swinging frame, of a flexible device connected thereto, means for locking said frame in a predetermined position, and mechanism for exerting a pull on said flexible device to cause the latter to engage material over an intermediate portion of said device to effect the removal of material from a mine wall transversely with respect to said device.
60. 112. In mining apparatus, the combination with a swinging arm, of a rope connected to said arm, of means for operating said arm to move said rope into a kerf in the mine wall, a locking device for holding said arm in a predetermined position, and means for exerting a pull on said rope to pry the material away from the mine wall.
65. 113. In mining apparatus, the combination with a frame, of an arm pivoted to said frame, a flexible device connected to the outer end of said arm, means for swinging said arm to extend said flexible device into a kerf in a mine wall, locking mechanism for holding said arm in a predetermined position.

tion, and winding mechanism for exerting a pull on said flexible device to move material from the mine wall and break up the same.

5 114. In a mining machine, the combination with a main frame comprising lateral upright supporting standards, of a supplemental frame pivoted to said upright standards for tilting movement between the same, 10 a forwardly extending bracket at the upper portion of said supplemental frame to form a supporting fork with the lower portion of said supplemental frame, core-cutting mechanism pivotally mounted between the arms 15 of such fork for swinging movement on an upright axis, and means for operating said core-cutting mechanism including the feed thereof by swinging the same on such upright axis between the forwardly extending 20 arms of such supporting fork.

115. A mining and loading machine comprising a supporting frame, loop chain core-cutting mechanism mounted on said frame, said loop chain core-cutting mechanism having an unobstructed core-opening therethrough, means operating relatively to said frame and back of the core to dislodge the latter, said dislodging means being mounted on said frame and extending out therefrom, 25 and means in position on said frame for receiving the dislodged material directly from the space occupied thereby in its native bed.

116. A mining machine comprising a platform, a radial frame pivotally mounted 30 on said platform and having an unobstructed core-opening therethrough, core cutting mechanism mounted on said radial frame, dislodging mechanism connected to said frame, and loading apparatus mounted on 35 said platform.

117. In mining apparatus, the combination with loop chain cutting mechanism, of means for feeding said cutting mechanism over a predetermined arc of a circle, and an 40 arc-shaped receiving platform having a curvature at its forward end substantially the same as the predetermined arc of movement of said cutting mechanism, and occupying a position close to the mine wall throughout 45 its maximum arcuate periphery during the cutting operation.

118. In mining apparatus, the combination of means for severing a section of material from a mine wall, and a receiving 55 platform having a forward edge close to the mine wall throughout the length of said edge corresponding in contour to the path of the farthermost reach of said severing means and to the contour of the severed mass.

119. A mining and loading machine comprising a frame having a platform for receiving dislodged material directly from a mine wall, mechanism mounted on said frame for cutting a single core of material 60 in the mine wall by producing a continuous

kerf therein entering and emerging from the mine wall at spaced-apart locations, said cutting mechanism having an unobstructed core-opening therethrough, means for operating said cutting mechanism including 70 feeding movement thereof relatively to said frame, means mounted on said frame for moving the cut material directly from its cut position onto said platform and along the same toward loading position, and means 75 for adjusting the elevation of said platform for varying the position thereof in accordance with the height of the cut material.

120. A mining apparatus comprising a loop chain cutter, a platform having its forward edge adjacent the lowermost length 80 of said chain cutter, and automatic means for moving the cut material from its natural ledge below the body of the cut material onto said platform. 85

121. A mining and loading machine comprising a movable platform, a radial frame pivotally mounted on said platform in a plane transverse to the plane of said platform having an unobstructed core opening 90 therethrough, endless chain cutting mechanism guided on said frame, dislodging mechanism connected to said frame, and loading mechanism for receiving material 95 from said dislodging mechanism.

122. A mining machine comprising a loop chain cutter, a platform in close proximity to the lower length of said cutter, said platform being in a plane transverse to the plane of said chain cutter, and means for operating 100 said chain cutter to cut a core of material in a mine wall along the forward edge of said platform and in close proximity thereto throughout its length.

123. A mining machine comprising cutting mechanism mounted in an upright plane and having an unobstructed core-opening therethrough, a platform in a plane transverse to the plane of said cutting mechanism and in position to receive the cuttings 110 from said cutting mechanism during the entire path of feeding travel of said cutting mechanism, means for operating said cutting mechanism including the feed thereof, and mechanism for adjusting the height of 115 both the cutting mechanism and said platform while retaining the relation between them substantially the same.

124. In a mining machine, the combination with cutting mechanism mounted in 120 an upright plane and having a single unobstructed core-opening therethrough, of a platform having its upper surface in substantially the same plane as the lower surface of the cut produced by said cutting mechanism, and means for dislodging the cut material directly from the mine wall 125 onto said platform.

125. In a mining machine, the combination with core cutting mechanism having 130

- a portion emerging from the mine wall during operation, of a platform extending to a position close to the mine wall and in close proximity to the place where said cutting mechanism emerges from the mine wall, means for adjusting the elevation of said platform together with said cutting mechanism, and means for dislodging the cut material onto said platform.
- 10 126. A mining machine comprising a supporting frame, a platform on said frame and extending to a position adjacent the upright face of a mine wall, core-cutting mechanism mounted on said frame and extending therefrom in position to cut a core in the mine wall beyond the forward end of said platform, and automatic means for dislodging cut material from the mine wall beyond the forward end of said platform and moving such dislodged material from the mine wall onto said platform.
- 15 127. In a mining machine, the combination with a main frame of a supplemental frame mounted for vertical adjustment on said main frame, means on the supplemental frame for simultaneously cutting connecting kerfs to produce a core of material in its native bed, a platform on said supplemental frame having a predetermined relation to said cutting means, means for adjusting the position of said cutting means together with said platform, and means for removing said cut material from the mine wall and sliding the same over said platform.
- 20 128. In a mining machine, the combination with core cutting mechanism, of a platform having a predetermined relation thereto, means for adjusting the elevation of said platform together with said core cutting mechanism without changing the relative relation between the same, said platform being always in position to receive the dislodged material directly from the position occupied thereby in its native bed irrespective of the height thereof from the mine floor within predetermined limits, and means for sliding the dislodged material over said platform toward loading position.
- 25 129. A mining machine comprising loop chain core cutting mechanism, means for supporting the same pivotally in a radial plane, means for operating said chain cutter to cut a core of material in its native bed, a platform in a plane at right angles to the plane of said core cutting mechanism, a flight conveyer arranged approximately in the plane of said platform, and means for removing the cut material from the mine wall over said platform onto said conveyer.
- 30 130. In a mining machine, the combination with loop chain core cutting mechanism occupying an upright plane, a supporting frame comprising a platform having an arcuate forward edge, means for swinging
- the loop chain core cutter along the arcuate forward edge of said platform, and means for actuating said loop chain core cutter to emerge from the mine wall adjacent said arcuate edge to scrape the cuttings from the 70 kerf onto said platform and back from the forward edge thereof.
- 35 131. In a mining machine, the combination with core cutting mechanism, of a platform for receiving the core, a belt for dislodging the core from the mine wall onto said platform, a conveyer for moving the said dislodged material toward loading position, and mechanism coöperating with said belt to move the material off said platform 80 onto said conveyer.
- 40 132. A mining machine comprising a loop chain core cutter, a platform to receive the material cut by said loop cutter, a belt, means for operating said belt to move the 85 cut material onto said platform, a conveyer for moving the material into position for loading into mine cars, and means coöperating with said belt to guide the cut material onto said conveyer.
- 45 133. In mining apparatus, the combination with core-cutting mechanism for severing a section of material from a mine wall, of a platform having a forward edge corresponding to the contour of the cut produced by said cutting mechanism, and means for adjusting the position of said platform.
- 50 134. In mining apparatus, the combination with a loop chain core cutter, of means for feeding said cutter over an arcuate path 100 of travel, an arc-shaped device for collecting the cuttings from said chain cutter, and means for adjusting the position of said collecting device.
- 55 135. In mining apparatus, the combination with a frame, of a loop chain cutter mounted on said frame, means for operating said cutter in an arcuate path, and means continually adjacent said chain cutter for receiving substantially all of the cuttings 110 directly therefrom.
- 60 136. In mining apparatus, the combination with loop chain core cutting mechanism, of means for operating the same, means for feeding said cutting mechanism 115 in an arcuate path, and an extensible platform having its forward edge adjacent the mine wall and corresponding in curvature to the arcuate path of said cutting mechanism, and adjustable in position to receive 120 cuttings from said loop chain core cutting mechanism directly from the mine wall at various heights.
- 65 137. In a mining machine, the combination with a main frame, of a supplemental 125 frame pivoted to said main frame for tilting movement of its forward portion up and down, loop chain core cutting mechanism mounted on the forward portion of said supplemental frame, and means for operating 130

said core cutting mechanism including the feeding thereof in an arcuate path across the mine wall, and an extensible platform having an arcuate forward edge to receive the cuttings from the chain cutter as the latter emerges from the mine wall and adjustable to compensate for the tilting movements of said supplemental frame.

138. In a mining machine, the combination 10 with core cutting mechanism, of means for operating the same including arcuate feed thereof, a platform for receiving material directly from its cut position in the mine wall throughout the arcuate path of travel 15 of said cutting mechanism, said platform being sectional and foldable laterally to diminish the width of the mining machine during transportation.

139. In a mining machine, the combination 20 with core cutting mechanism, of means for operating the same including arcuate feed thereof, a supporting frame, a platform slidably connected to said supporting frame and in position to receive material directly 25 from its cut position in the mine wall throughout the arcuate travel of said cutting mechanism, and means for adjusting the position of said platform relatively to said supporting frame.

140. In a mining machine, the combination 30 with a supporting frame, of an extensible platform mounted thereon and comprising relatively movable sections with the forward section adjacent the mine wall, 35 means for adjusting the platform with its forward end in receiving positions at various elevations adjacent the mine wall between the floor and roof of the mine chamber, and means mounted on said frame and extending 40 therefrom in position to take material from the mine wall directly above the forward end of the platform irrespective of the elevation thereof between such floor and roof, and sliding such material from its position 45 in the mine wall directly onto the upper surface of said platform.

141. In a mining machine, the combination 50 with cutting mechanism for cutting a core in one operation, of means for operating the same including arcuate feeding thereof, a conveyer, and means in position throughout a range of approximately 180 degrees for guiding cuttings directly from the mine wall and said cutting mechanism 55 onto said conveyer.

142. In a mining machine, the combination 60 with loop chain core cutting mechanism, of means for swinging the same including the feed thereof, in an arcuate path, a conveyer, a platform having an arcuate forward portion to conform to the arcuate feeding path of said cutting mechanism, and a semi-circular beveled guide for directing cuttings from said cutting mechanism onto 65 said conveyer.

143. In a mining machine, the combination 70 with cutting mechanism, of a flat frame, a flight conveyer mounted on the upper surface thereof, and an inclined approach for the forward portion of said frame to said conveyer, said cutting mechanism moving material over said approach onto said conveyer.

144. In a mining machine, the combination 75 with a frame having a longitudinal recess, a flight chain conveyer in said recess, cutting mechanism for producing a core in one operation, and means for guiding the cuttings from said cutting mechanism into said recess for various positions of said cutting mechanism.

145. In mining apparatus, the combination 80 with cutting mechanism, of a platform for receiving the cuttings from said cutting mechanism, a conveyer, and a belt mounted vertically on said platform for moving said cuttings from said receiving device onto said conveyer.

146. In mining apparatus, the combination 85 with a loop chain cutter, of a conveyer, a platform for receiving the cuttings from said chain cutter, means for adjusting the position of said platform relatively to said chain cutter, and a vertical belt for moving the cuttings onto said conveyer.

147. In mining apparatus, the combination 90 with a swinging arm, of a flexible device connected to said arm, means for moving said arm to extend said flexible device into a kerf in a mine wall, a winding drum 100 for exerting a pull on said flexible device, and means for holding said winding drum in a predetermined position.

148. In mining apparatus, the combination 105 with a chain cutter and means for operating the same, of rope drum gearing for advancing the chain cutter while the same is operating, a conveyer, a flexible device, means for exerting a pull on said flexible device for restoring the cutter to initial position, and means for directing the material onto the conveyer while co-operating with said flexible device to break up the material cut out by said cutter.

149. In mining apparatus, the combination 115 with a supporting frame, of cutting mechanism mounted thereon, a flexible device mounted on said frame, a platform on said frame, a conveyer mounted on said frame, means for supporting said flexible device above the plane of said platform, and means for exerting a pull on said flexible device to act on the material in its cut position in a mine wall to break said material and slide the same over said platform onto 120 said conveyer while said flexible device continues to extend above the plane of said platform.

150. A mining machine comprising a 125 drum, and power mechanism for taking ma- 130

terial directly from its position in a mine wall and moving it against said drum to break said material.

151. A mining machine comprising a drum, and means spaced apart from said drum but coöperating therewith for taking material directly from a mine wall and breaking up the same.

152. A mining machine comprising a frame, a cylinder mounted on said frame for movement circumferentially, and means coöperating with said frame and cylinder for taking material directly from a mine wall and breaking up the same.

153. A mining machine comprising a supporting frame, of a swinging frame pivoted thereto, and having a spider arm hub, a flexible device connected to said swinging frame, and means for operating said flexible device by taking material directly from its native position in a mine wall and pressing it against said hub to break up said material.

154. In mining apparatus, the combination with a supporting frame, of cutting mechanism mounted thereon, a flexible device mounted on said frame, a conveyer having a receiving portion above the plane in which the flexible device extends, means for exerting a pull on said flexible device to act on the material in its cut position in a mine wall to break said material from the mine wall, and means coöperating with said flexible device for directing the broken material onto said receiving portion of said conveyer.

155. In mining apparatus, the combination with cutting mechanism, mounted on a frame, a flexible device connected to the outer end of said frame, locking mechanism for holding said frame in a predetermined position, a winding drum for said flexible device, means for operating said winding drum to exert a pull on said flexible device when said frame is locked in the said predetermined position, and loading apparatus for moving the material back away from the mine wall.

156. In mining apparatus, the combination with a chain cutter, of a frame for carrying said chain cutter having an opening therethrough to permit the chain cutter to extend around the material cut from the mine wall, means for swinging said frame and chain cutter laterally to advance the same during the cutting operation, a flexible device connected to the outer end of said frame, latch mechanism for locking the frame and chain cutter against being retracted after the chain cutter reaches the limit of travel, a winding drum, a platform, means for operating said winding drum to exert a pull on said flexible device to break up the material cut from the mine wall by said chain cutter and move said material onto said platform, a lever for releasing said latch mechanism, a cylindrical drum carried

by said chain cutter frame and movable therewith during retraction thereof to direct the broken up material toward the rear of said platform, and a conveyer for receiving the broken down material as it is moved toward the rear and for moving said material farther toward the rear for the purpose of loading into mine cars.

157. In mining apparatus, the combination with a loop chain core cutter, of means for operating the same to dislodge a crescent-shaped block of material from a mine wall, means for bodily moving said block of material from its cut position in the mine wall, a cylindrical drum coöperating with said moving means for breaking up said block of material into smaller sections, and means for receiving said smaller sections of material and moving the same into position for loading into mine cars.

158. In mining apparatus, the combination with a loop chain cutter and means for moving the same laterally to cut out a block of material, of mechanism for operating said chain cutter, loading apparatus, means including a flexible device for bodily moving said block of material from its cut position in the mine wall toward said loading apparatus, and a rotatable cylindrical drum coöperating with said flexible device for breaking up said block of material into smaller sections and directing the same to said loading apparatus.

159. A mining and loading machine comprising a supporting frame, a loop chain core-cutter mounted thereon, means for operating said core-cutter by swinging the same relatively to said frame, and power mechanism mounted on said frame and extending therefrom in position to act on the core immediately after being cut to dislodge the same and take the dislodged material directly from the space originally occupied thereby in the mine wall and move it toward loading position.

160. In mining apparatus, the combination with a loop chain cutter, of a platform, a conveyer, and means including a vertical belt for dislodging the material from the mine wall breaking up the material, and moving it over said platform onto said conveyer.

161. In mining apparatus, the combination with a chain cutter, of means for operating the same, means for feeding said chain cutter substantially at right angles to the plane thereof to cut a core of material in a mine wall, power mechanism connected to said chain cutter for breaking up the material cut thereby, and automatic mechanism for moving the broken up material into position for loading.

162. In a mining machine, the combination with a main frame, of a supplemental frame mounted for vertical adjustment on

said main frame, loop chain core cutting mechanism on said supplemental frame, a platform on said supplemental frame having a predetermined relation to said cutting mechanism over an arcuate travel of the latter of approximately 180 degrees, means for adjusting the position of the cutting mechanism together with said platform to various elevations, and means for removing cut material directly from the mine wall onto said platform.

163. In a mining machine, the combination with loop chain core cutting mechanism, of means for operating the same, a frame for supporting said cutting mechanism and said operating means; a platform, automatic mechanism for moving substantially all the cut material directly back from the mine wall from its cut position onto said platform, and guides for directing the material over said platform into position for loading into mine cars.

164. A mining and loading machine comprising a supporting frame, an oblong loop chain core-cutter extending outwardly from said frame, said core-cutter having an unobstructed core-opening therethrough of a larger dimension in a general horizontal direction than in an upright direction, means mounted on said frame for operating said loop chain core-cutter including the feed thereof transversely to the plane thereof, and automatic mechanism mounted on said frame for dislodging the cut material from its cut position in a mine wall directly after being cut.

165. In a mining machine, the combination with a supporting frame, of an endless chain core-cutter having an unobstructed core-opening therethrough at its outer portion and upper and lower portions for cutting spaced-apart plane kerfs, a single driving sprocket for said chain-cutter, means for operating said chain-cutter including arcuate feed thereof, and means for adjusting the chain-cutter as a whole to various elevations to predetermine the height of the core cut from a mine wall.

166. In a mining machine, the combination with chain cutting mechanism for cutting a core in one operation, of conveyer mechanism, and means for transmitting power through said conveyer mechanism to said core cutting mechanism to effect the actuation of the latter.

167. In a mining machine, the combination with an upright loop chain core cutter, of a supporting frame, means for swinging said loop chain cutter on an upright axis on said supporting frame, a conveyer mounted on said frame in a plane transverse to that of the loop chain cutter, means for operating the conveyer, and means intermediate the conveyer and the loop chain cutter and

associated with the swinging axis of said loop chain cutter for actuating the latter.

168. In a mining machine, the combination with a supporting frame, of a plane conveyer mounted thereon a loop chain cutter, a loop chain cutter frame mounted to swing on an upright axis, means for swinging said loop chain cutter frame to secure feeding movement of said loop chain cutter, mechanism intermediate the conveyer and said loop chain cutter to effect transmission of power to the latter from said conveyer and means for transmitting power direct to said conveyer.

169. A mining and loading machine comprising a supporting frame, core-cutting mechanism mounted thereon, a platform carried by said frame, and means including a flexible device mounted on said frame and extending therefrom for breaking the material cut out by said cutting mechanism and moving said material onto said platform directly from the position in the mine wall in which such material is cut.

170. A mining and loading machine comprising a supporting frame, mechanism mounted on said frame for cutting a core of material in a mine wall, means for operating said core-cutting mechanism including the feed thereof through a range of 180 degrees or more, and means in position on said frame for receiving dislodged material and effecting mechanically the transfer thereof from the mine wall toward loading position.

171. A mining and loading machine comprising a supporting frame, mechanism mounted on said frame for cutting in a mine wall a section of material, and means mounted on said frame in position for automatically taking the dislodged material from the mine wall where cut and effecting the transfer thereof for loading position.

172. A mining and loading machine having supporting framework in common, core-cutting mechanism mounted on said framework in position for cutting cores in a mine wall, adjacent said framework, and loading apparatus mounted on said framework in fixed relation thereto for taking the material directly from its originally occupied position in the mine wall and moving it toward loading position.

173. A mining and loading machine comprising a supporting frame, a loop chain core-cutter mounted on said frame for movement up and down as a whole with said frame, a conveyer mounted on said frame for up and down tilting movement with said cutter, means for effecting the transfer of cut material onto said conveyer, and means for operating the conveyer to load the material received thereby.

174. A mining and loading machine comprising core-cutting mechanism, a frame

- for supporting said core-cutting mechanism in an upright plane, a conveyer mounted on said frame and tiltable bodily with said core-cutting mechanism, means for operating said core-cutting mechanism, means for operating said core-cutting mechanism, means for operating said conveyer, and automatic mechanism under the control of the operator for effecting the transfer of the cut material from the cutting mechanism to said conveyer.
175. In a mining and loading machine, the combination with mechanism for cutting a core in a mine wall in one operation, of mechanism connected to said cutting means for acting on the core to gradually break the same during the operation of said cutting means, apparatus for intermittently operating said breaking mechanism, and means for receiving the dislodged material and moving it toward loading position.
176. A mining and loading machine comprising a supporting frame, kerf-cutting mechanism for cutting a U-shaped kerf in a mine wall, said kerf-cutting mechanism having its cutters extending forwardly when in initial position, means mounted on said frame for operating said kerf-cutting mechanism to produce a substantially U-shaped kerf and a crescent-shaped core of material in a mine wall, and loading apparatus entirely mechanical and mounted on said frame for automatically moving back from the mine wall the material dislodged by the production of said U-shaped kerf.
177. A mining and loading machine comprising a supporting frame, kerf-cutting mechanism mounted on said frame with its cutters extending forwardly when in initial position, means mounted on said frame for operating said kerf-cutting mechanism relatively to said frame for producing a substantially U-shaped kerf and a crescent-shaped core of material in a mine wall, and loading apparatus extending into a position in the path of said kerf-cutting mechanism and mounted on said frame for automatically moving back from the mine wall substantially all of the material dislodged by the production of said U-shaped kerf.
178. A mining and loading machine comprising a frame, cutters mounted thereon to cut simultaneously a pair of separated kerfs and a back kerf connecting said separated kerfs, means for operating said cutters including the feed thereof during actuation to cut a column of material in its native bed adjacent said frame, a platform on said frame in position for receiving material cut by said cutters, and means mounted on said frame for moving the dislodged material over said platform toward loading position.
179. In a mining machine, the combination with cutters arranged to cut separated kerfs and a back kerf connecting said separated kerfs, of an open frame carrying said cutters, means for operating said cutters including the feed thereof by movement of said open frame, to cut a column of material extending through said frame, means for moving the frame upward, and removing means comprising mechanism located in one of said kerfs to catch and carry off the falling material.
180. A mining and loading machine comprising a supporting frame, means mounted on said frame for severing a core of material from a mine vein by a kerf encircling the core on the sides thereof not previously detached, and means mounted on said frame and adjustably spaced from said severing means for displacing said core laterally from its native bed in a mine vein.
181. A mining and loading machine comprising a supporting frame, means mounted on said frame for dislodging material from a mine wall, a conveyer connected to said frame in fixed relation thereto and movable bodily therewith, and means movable relative to said frame and relatively to said conveyer for acting on the material in the position which it assumes after being dislodged to slide such material onto said conveyer.
182. A mining and loading machine comprising a supporting frame, bodily movable cutting mechanism mounted thereon and adapted to entirely sever a block of material from an unmined mass, and means mounted on said frame for removing said block of material from the space occupied thereby in its native bed along the line of movement of said cutting mechanism.
183. A mining and loading machine comprising a supporting frame, kerf-cutting mechanism mounted thereon, means for operating said kerf-cutting mechanism including the feed thereof to cut a core of material in a mine wall, conveying mechanism mounted on said frame in fixed relation thereto, and means mounted on said frame and movable relatively thereto to act on the material at the mine wall to transfer the same onto said conveyer.
184. A mining and loading machine comprising a supporting frame, kerf-cutting mechanism mounted thereon, means for operating said kerf-cutting mechanism including the feed thereof to effect the cutting of a kerf above a core of material at the back thereof spaced in the face of the mine wall and below the core, a conveyer mounted on said frame in fixed relation thereto, and power mechanism mounted on said frame for delivering the material of said core to said conveyer.
185. A mining and loading machine comprising a supporting frame, means mounted thereon for cutting a U-shaped kerf in a

mine wall in a general horizontal direction, mechanism mounted on said frame for movement relatively thereto for dislodging the cut material, and conveyer mechanism in position on said frame for receiving dislodged material and conveying it rearwardly toward loading position.

186. A mining and loading machine comprising a supporting frame, of mechanism mounted thereon and extending therefrom to cut a core of material along a mine wall, means mounted on said frame and extending therefrom on the side from which said cutting mechanism extends for dislodging the cut material, and conveyer mechanism connected to said frame and movable bodily therewith in position for taking the dislodged material and moving it to a position in the wake of the machine.

187. A mining and loading machine comprising a supporting frame, means mounted thereon and extending therefrom to cut a core of material in a mine wall adjacent said frame, endless conveyer mechanism mounted on said frame in predetermined relation thereto and for movement bodily therewith, and intermediate mechanism on said frame and extending from a position at the same side of the frame from which said core-cutting mechanism extends for effecting the transfer of dislodged material from the mine wall onto said conveyer mechanism.

188. The combination of a loop-shaped cutting mechanism arranged to simultaneously cut a plurality of kerfs at an angle to each other to entirely sever a block of coal from the vein, means for bodily moving said cutting mechanism to remove the block of coal from its original relative position, and means for directing said block of coal away from the cutting mechanism.

189. A mining and loading machine comprising a supporting frame, core-cutting mechanism mounted on said frame and adapted to produce kerfs comprising a lower frame kerf, means for operating said core-cutting mechanism including the feed thereof, means for reversing the movement of said core-cutting mechanism and causing it to engage the core of material and move it away from its cut position in the mine wall, a conveyer mounted on said frame to extend toward loading position, and mechanism for directing the core of material onto said conveyer when said cutting mechanism is reversed to move said core away from its position in a mine wall.

190. A mining and loading machine comprising a supporting frame, mechanism mounted thereon for cutting a solid core of material along a mine wall, means mounted on said frame for dislodging the cut material, and mechanism in position on said frame for taking the dislodged material from its native position and moving it to-

ward loading position at the rear of said frame.

191. A mining and loading machine comprising a supporting frame, means on said frame for cutting a U-shaped kerf in a mine wall, means in position on said frame to act directly on the material while in its cut position to break it away from the mine wall while said frame remains in the position occupied thereby during the cutting of said U-shaped kerf, and conveyer mechanism mounted on said frame in position for receiving the dislodged material from said breaking means and moving such dislodged material toward loading position. 80

192. A coal mining and loading machine comprising a main frame, means carried by said main frame for forming a core out of the coal in its native bed by cutting the top, bottom and rear of said core, means for operating said core-forming means including feed thereof relatively to said main frame while the latter remains stationary, means for engaging said core to dislodge it, mechanism for operating said dislodging means while said main frame remains in such stationary position, such dislodging means operating relatively to said frame in the space occupied by said core, and means mounted on said frame for moving the dislodged material toward loading position while said main frame remains in the same stationary position. 90

193. A mining and loading machine comprising a frame, means for anchoring said frame to hold the same stationary, mechanism mounted on said frame for cutting a core of material in a mine wall, means movable relatively to said frame and mounted thereon in position to dislodge said core, conveying mechanism mounted on said frame in position for taking the dislodged material toward loading position, means for operating said cutting mechanism while said frame remains anchored, means for operating said dislodging means while said frame remains anchored, and means for operating said conveying mechanism while such frame remains anchored, said frame being anchored in the same position during the cutting, dislodging and removal of a predetermined section of material from the mine wall. 105

194. A mining and loading machine comprising a main frame, a supplemental frame mounted on said main frame for tilting movement on an axis extending transversely of said main frame, a loop chain core-cutter having an unobstructed core-opening therethrough and mounted for swinging movements on an upright axis on said supplemental frame between the forwardly extending arms thereof having an open space between them, means for holding the supplemental frame in adjusted tilted position on said main frame to hold said core-cutter for 120 125 130

- operation across the mine wall in a general horizontal direction, and means for operating said core-cutter by swinging the same on its upright axis on said supplemental frame 5 while said main frame and said supplemental frame remain stationary to cut a single core across the mine wall in a general horizontal direction in one operation and another single core at a different elevation 10 while said main frame remains substantially in the same position as before.
195. A mining and loading machine comprising a supporting frame, mechanism mounted on said frame for cutting an arc-shaped kerf spaced back from the face of a mine wall adjacent said frame, means mounted on said frame in position to extend into said kerf to dislodge material directly from the mine wall between said kerf and the face of the mine wall adjacent said frame, means for operating said cutting mechanism to cut said arc-shaped kerf while said supporting frame remains stationary, and mechanism for operating said dislodging means relatively to said supporting frame and while the latter remains stationary.
196. The combination with cutting mechanism movable in an arc for entirely severing a block of material from the mass thereof, means for bodily moving said cutting mechanism to remove the severed block, and a receiving structure disposed in an arc the center of which is at the center of the arc of movement of said cutting mechanism for receiving the blocks as they are removed by the cutting mechanism to direct said blocks beyond the cutting mechanism.
197. A mining and loading machine comprising, a supporting frame, kerf-cutting mechanism mounted on said frame and bodily movable along a curved path for entirely severing a block of coal from its native bed in a mine, and mechanism mounted on said frame in position for removing said block of coal along such curved path while said block remains intact and while said frame remains in the same position it occupied during the operation of said kerf-cutting mechanism.
198. The combination with a loop-shaped cutting mechanism arranged to simultaneously cut a plurality of kerfs at an angle to each other to entirely sever a block of coal from the vein, means for bodily moving said cutting mechanism to remove the block of coal from its original relative position, and means, embodying a receiving chute, positioned in alignment with the line of movement of said cutting mechanism for directing the block of coal away from said cutting mechanism.
199. In a mining machine, the combination with a supporting frame, of a cutter-frame mounted for arcuate movement on an upright axis on said supporting frame and having an unobstructed core-opening therethrough, an endless chain-cutter extending laterally from one side of said cutter-frame and guided along the same, actuating mechanism for said endless chain-cutter having a plane of drive between the cutting portion of said chain-cutter and said cutter-frame substantially parallel to the plane of said cutter-frame, and means for effecting arcuate feed of said cutter and cutter-frame during the actuation thereof to cut a core in a mine wall.
200. A mining and loading machine comprising a frame, of loop chain-core-cutting mechanism mounted thereon, means for operating said core-cutting mechanism, and conveyer mechanism mounted on said frame in fixed relation thereto to move bodily with said frame while remaining in position for transferring the cut material toward loading position.
201. In a mining and loading machine, the combination with a supporting frame, of loop chain core-cutting mechanism, means for operating said core-cutting mechanism, and loading apparatus mounted on said frame and extending to the mine wall for taking the cut material therefrom along a plane extending through the lower portion of said core-cutting mechanism and moving such material along said frame toward loading position.
202. A mining and loading machine comprising a supporting frame, cutting mechanism mounted thereon, and embodying a cutting chain traveling in a loop and adapted to surround the block of coal which it cuts, means for operating said cutting mechanism, means for returning said cutting mechanism toward initial position and causing it to engage the block of coal to move the same away from its cut position in the mine wall, and a chute on said frame in position to receive one end of said block of coal and direct the same toward loading position.
203. The combination of bodily movable cutting mechanism embodying cutting means for cutting a plurality of kerfs angularly disposed with respect to each other, and adapted to embrace the block of coal as it is cut, means for operating said cutting mechanism, means operable on the return stroke of said cutting mechanism for removing the block from its original position along the line of movement of said cutting mechanism, and a receiving structure in position relatively to said cutting mechanism for directing the block of coal away from the cutting mechanism.
204. A mining and loading machine comprising a frame, core-cutting mechanism mounted on said frame and adapted to produce kerfs in a mine wall comprising a lower plane kerf adjacent said frame, means

- for operating said core-cutting mechanism, means for reversing said core-cutting mechanism and causing that portion thereof passing through the lower plane kerf to engage 5 the cut material and move it out of its cut position in the mine wall, a conveyer mounted on said frame and extending longitudinally thereof toward the rear, and a chute between the receiving portion of said 10 conveyer and the forward portion of said frame for directing the cut material from the mine wall onto said conveyer.
205. A mining machine comprising a supporting frame, a core-cutter mounted on 15 said frame, means for operating said core-cutter including the feed thereof in feeding direction, and separate means connected to the outer portion of the core-cutter remote from said frame for moving the core-cutter 20 in reverse direction.
206. A mining machine comprising a supporting frame, core-cutting mechanism mounted thereon, rope gearing for moving 25 said core-cutting mechanism in feeding direction but incapable of moving the same in the reverse direction, a flexible member connected to said cutting mechanism for movement into one of the kerfs produced by said cutting mechanism, and means for 30 exerting a pull on said flexible member to retract said cutting mechanism and guide the core of material away from the mine wall when moved therefrom by being engaged by the back side of said core-cutting 35 mechanism.
207. A mining machine comprising loop chain core-cutting mechanism having an unobstructed core-opening therethrough, means for operating the same to cut a core by 40 cutting kerfs, a rope drive for effecting the feeding of said loop chain core-cutting mechanism during its operation, said rope drive being ineffective for return movement of said core-cutting mechanism, a flexible 45 member connected to the outer end of said core-cutting mechanism to be drawn into the kerf back of the core, and means for exerting a pull on said flexible member to 50 retract said cutting mechanism while its back side engages the core and moves it away from the mine wall, said flexible member guiding the core to a predetermined position and assisting in the withdrawal of said core from the mine wall.
- 55 208. A mining machine comprising kerf-cutting mechanism having an unobstructed core-opening therethrough, means for operating said kerf-cutting mechanism to cut a core in a mine wall with one end remaining 60 integral therewith, means for actuating said kerf-cutting mechanism, rope-gearing for feeding said cutting mechanism during the actuation thereof, a flexible device connected to the outer portion of said kerf-cutting mechanism to enter the kerf back of the core, and means for exerting a pull on said flexible device to break off a portion of said core and reverse the movement of said core-cutting mechanism to cause the back side thereof to engage the broken-off piece of 65 the core and move it away from the mine wall while said flexible device assists in directing the dislodged core piece to a predetermined position spaced back from the mine wall.
- 70 209. In a mining machine, the combination with cutting mechanism, of means for operating said cutting mechanism to effect the dislodgement of a crescent-shaped section of material from a mine wall, and 75 flexible means connected to said cutting mechanism for engaging the dislodged section of material and moving the same back from the mine wall.
- 80 210. In a mining machine, the combination with core-cutting mechanism, of a belt connected to said cutting mechanism, means for exerting a pull on said belt to retract said core-cutting mechanism together with the severed material, and a guide for directing the material to a predetermined loading position.
- 85 211. In a mining machine, the combination with a frame, of a loop cutter mounted thereon, means for operating said loop cutter to sever a section of material from a mine wall, flexible means connected to said loop cutter and entering the mine wall therewith, mechanism for exerting a pull on said flexible means to cause 90 the same to move the severed section of material back from the mine wall, and a conveyer for continuing the movement of the severed material to loading position.
- 95 212. The combination of a frame, a rotary cutting mechanism positioned at the forward end of said frame and arranged to cut a crescent-shaped section of material from the wall of a mine, a cable attached to the cutting mechanism to be drawn into the kerf by the rotation thereof into direct engagement with the cut section of material, and means at the rear of the machine for pulling upon said cable to restore the cutting mechanism and discharge the section from the rear end of the frame.
- 100 213. In a mining machine, the combination with a supporting frame comprising a platform extending across a mine wall in a general horizontal direction, of loop chain core-cutting mechanism having an unobstructed core-opening therethrough and mounted on said supporting frame in an upright plane with its lower run adjacent said platform, a conveyer mounted on said frame and extending to a forward position near the lower run of said loop chain core-cutting mechanism, and means for operat- 105 110 115 120 125

ing said loop chain core-cutting mechanism to cause the same to cut a core in the mine wall and to emerge therefrom along its lower run to cause the cuttings from said cutting mechanism to move over said platform onto said conveyer.

214. In a mining machine, the combination with a loop chain core-cutter, mounted for operation in an upright plane, of means for operating the same, a supporting frame comprising a platform, and an adjustable extension on said platform for collecting the cuttings automatically from said cutter.

215. In a mining machine, the combination with a platform, of a cutter head mounted on said platform for rotation about an upright axis, a loop core cutter on said cutter head and movable therewith, and a rotatable abutment carried by said cutter head.

216. In a mining machine, the combination with a frame, of curved means carried by said frame and movable relatively thereto into a kerf in a mine wall for breaking a core of material therefrom, and a conveyer mounted on said frame for receiving the material from said breaking means and moving it toward loading position.

217. A mining and loading machine comprising a supporting frame, means mounted on said frame for cutting a single core of material in its native bed in a mine, means mounted on said frame in position for breaking the core into large blocks independently of movement of said frame, and means mounted on said frame for moving the dislodged blocks of material from the mine wall relatively to said frame and toward loading position independently of the movement of said frame.

218. A mining and loading machine comprising a frame, means mounted thereon for cutting a core of material in its native bed adjacent said frame, mechanism mounted on said frame in position to act directly on the core while still in its native position for breaking sections from such core during the operation of said core-cutting means, and mechanism mounted on said frame in position for taking dislodged material immediately after being dislodged and moving the same toward loading position while said core-cutting means continues in operation.

219. A mining and loading machine comprising means for cutting spaced-apart kerfs at the sides of a column of material in its native bed and also a communicating kerf at the back of such column, a supporting frame for such cutting means, conveyer mechanism mounted on said frame and extending from a forward position near the cutting mechanism rearwardly toward loading position, and means mounted on said

frame for effecting the transfer of the cut material directly from the mine wall onto said conveying mechanism.

220. A mining machine comprising a supporting frame, kerf-cutting mechanism for cutting spaced apart-kerfs and a vertical back kerf communicating with each other to cut a core in a mine wall leaving the forward end of said core integral therewith, mechanism mounted on said frame and extending therefrom in position to penetrate the vertical kerf and break up said core from the unmined mass.

221. A mining and loading machine comprising a supporting frame, cutting mechanism mounted thereon and extending therefrom in position for completely cutting out from a mine wall a section of material adjacent said frame, means for operating said cutting mechanism, apparatus mounted on said frame and extending therefrom on the same side from which said cutting mechanism extends for breaking up the section of material after being entirely cut away from the mine wall but while the said frame still remains adjacent the mine wall, and means mounted on said frame for operating said breaking apparatus by taking the section of material from its cut position in the mine wall and moving it onto said frame toward loading position.

222. A mining machine comprising a supporting frame, cutting mechanism mounted thereon for severing a crescent-shaped section of material from a mine wall adjacent said frame, means mounted on said frame and extending therefrom in position for moving said section of material in its entirety and intact back from the mine wall toward said frame, and mechanism mounted on said frame to coact with said moving means for breaking up such section of material while movement thereof toward loading position is continued.

223. In a mining machine, the combination with a loop chain cutter, of means for operating the same to sever a section of material from a mine wall, a supporting frame, an abutment secured to said frame, and means for bending the severed section of material against said abutment to break said material into smaller pieces.

224. In a mining machine, the combination with a loop chain cutter, of means for operating the same to sever a section of material from the mine wall, a curved abutment interlooping said loop chain cutter, and means for compressing said severed section of material against said abutment to break said material into smaller pieces.

225. In a mining machine, the combination with a loop chain cutter, of means for operating the same to sever a section of material from a mine wall, a supporting frame,

a cylinder fixed to said frame, a belt connected to the outer end of said chain cutter, and means for pulling said belt to cause the severed section of material against said 5 cylinder and break into smaller pieces.

226. The combination with a loop chain cutter, a U-shaped frame for said chain cutter, a swinging frame, supporting mechanism for said swinging frame, means for 10 adjustably securing the legs of said U-shaped frame to said swinging frame to enable the radial length of said loop chain cutter to be varied, mechanism for operating said chain cutter, and apparatus for slowly swinging 15 the chain cutter frame to feed the chain cutter during the cutting operation.

227. In a mining machine, the combination with swinging cutting mechanism having an unobstructed opening for the passage 20 of cut material therethrough, of means for operating said cutting mechanism, and means for adjusting the radial length of the plane of said cutting mechanism.

228. A mining and loading machine comprising 25 loop chain core-cutting mechanism having an unobstructed core-opening therethrough, means for operating said core-cutting mechanism including arcuate feed thereof, a main frame, a supplemental frame 30 carrying said core-cutting mechanism and mounted on said main frame to swing on a horizontal axis, a platform movable with said supplemental frame and in position to receive dislodged material from the mine 35 wall, and apparatus for moving such dislodged material along said platform toward loading position.

229. A mining and loading machine comprising a main frame, a supplemental frame 40 pivoted on said main frame on a horizontal axis, a loop chain cutter having an unobstructed opening therethrough and mounted on said supplemental frame, means for operating said cutter including the feed thereof 45 of to cut a column of material in the unmined mass, a platform on said supplemental frame, and means on said supplemental frame and extending therefrom in position for moving material dislodged from said 50 column over said platform toward loading position.

230. A mining and loading machine comprising a supporting frame, cutting mechanism mounted on said frame and having an 55 unobstructed opening therethrough, means for operating said cutting mechanism including feeding thereof through an arc to cut a column of material in the unmined mass adjacent said frame, and loading apparatus mounted on said frame and comprising a platform extending to a receiving 60 position adjacent the mine wall in a plane below the mass of said cut column.

231. A mining and loading machine comprising 65 a main frame, a supplemental frame,

mounted on said main frame to swing about an axis transverse to the vertical and longitudinal axes of said machine and above the floor of the mine chamber, loop chain core-cutting apparatus mounted on said supplemental frame and having an unobstructed core-opening therethrough, a platform on said supplemental frame extending to a position adjacent the mine wall to receive material dislodged from the cut core, and mechanism mounted on said supplemental frame and extending therefrom into position for moving the dislodged material over said platform toward loading position. 70

232. A mining and loading machine comprising 80 loop chain core-cutting mechanism and conveyer mechanism both angularly movable in an up and down direction, mechanism acting on the cut core for dislodging the same directly from its native position in the unmined mass, and a platform for the conveyer mechanism and in position for receiving from above the material dislodged by said dislodging mechanism. 85

233. In a mining machine, the combination 90 with a supporting frame, of loop chain core-cutting mechanism having an unobstructed core-opening therethrough and mounted on said frame, means for operating said core-cutting mechanism including forward feed thereof to cut a core of material in a mine wall adjacent said frame, a flexible device connected to the outer end of said core-cutting mechanism to be drawn by the forward feed of said cutting mechanism 100 into the kerf back of the core cut by said cutting mechanism, and means mounted on said frame for exerting a pull on said flexible device to return said cutting mechanism toward initial position while its back side engages the dislodged core section to remove said dislodged section from the mine wall onto said frame and while said flexible device guides such core section along said frame in a predetermined direction toward 110 loading position.

234. In a mining machine, the combination 115 with a frame having a platform, of means mounted on said frame for movement in an arc about an upright axis in position to engage dislodged material in advance of said frame, and mechanism for operating said arcuately movable means to engage dislodged material in advance of said frame and move such material arcuately onto said 120 platform.

235. In a mining machine, the combination 125 with kerf-cutting mechanism comprising a run in position to cut along the roof of a mine chamber, of a frame for supporting said kerf-cutting mechanism for arcuate feeding movement on an upright axis but inclined away from the upright face of the mine wall in an upward direction toward the roof of the mine chamber to secure the 130

cutting of a kerf, leaving the roof arch-shaped, and means for operating said kerf-cutting mechanism including arcuate feeding movement of such upright inclined axis 5 to secure such arch-shaped roof cut.

236. In a mining machine, the combination with a supporting frame, of a supplemental frame mounted to move in an arc on an upright axis on said supporting frame, 10 kerf-cutting mechanism comprising a traveling chain-cutter adapted to cut a plane kerf at the roof of a mine chamber when such upright axis is vertical, said kerf-cutting mechanism being mounted on said supplemental frame to move bodily therewith in an arc, means for operating said kerf-cutting mechanism including arcuate feed thereof on such upright axis, and means for adjusting said main frame to tilt such upright axis 15 and effect cutting by said traveling chain cutter of an arch-shaped roof in the mine chamber.

237. In a mining machine, the combination with a supporting frame, of core-cutting mechanism having an unobstructed core-opening therethrough and mounted on said frame for arcuate feeding movement on an upright axis but inclined rearwardly toward the roof of the mine chamber, said 20 core-cutting mechanism comprising a traveling cutter chain, means for operating said core-cutting mechanism including arcuate feeding movement thereof on such upright inclined axis in a general horizontal direction across the mine wall and along the roof of the mine chamber to cut a core of material in a mine wall and leave an arch-shaped supporting roof between the walls of the mine chamber.

40 238. In a mining machine, the combination with a supporting frame, of kerf-cutting mechanism mounted thereon for arcuate movement relative thereto through an angle of approximately 180 degrees on an upright 45 axis to cut a plane kerf approximately at right angles to such axis, means for adjusting said kerf-cutting mechanism to tilt such upright axis to effect the cutting of an arch-shaped supporting roof in a mine chamber, 50 and means for operating said kerf-cutting mechanism on such tilted axis including arcuate feed thereof through approximately 180 degrees relatively to said supporting frame to cut such arch-shaped supporting 55 roof.

239. In a mining machine, the combination with a supporting frame comprising a platform having an arcuate forward edge adapted to be located adjacent an upright 60 mine wall and abut against the same, of cutting mechanism mounted on said frame for arcuate movement on an upright axis, means for operating said cutting mechanism including arcuate feed thereof bodily relatively to said platform and along such arcu- 65

ate edge thereof, a conveyer having its receiving end at the rear portion of said platform, and means for moving severed material directly from the mine wall over the forward arcuate edge of said platform and 70 along the latter to the receiving end of said conveyer.

240. In a mining machine, the combination with a substantially horizontal platform, of a supplemental frame having an 75 exterior cylindrical surface and mounted on said platform for arcuate movement relatively thereto about an upright axis, core-cutting mechanism carried by said supplemental frame for movement therewith, said core-cutting mechanism having an unobstructed core-opening therethrough in position to permit said cylindrical surface to form an arcuate abutment as to the core cut by said cutting mechanism, and means for 80 operating said core-cutting mechanism including arcuate feeding movement thereof relatively to said platform to cut a core extending through said unobstructed core-opening and with its lower surface approximately in the plane of the upper surface of said platform.

241. In a mining machine, the combination with a main frame, of a supplemental frame having a substantially horizontal platform at its outer forward end for location adjacent an upright mine wall, means for moving said supplemental frame about a horizontal axis on said main frame to adjust the elevation of said platform, core-cutting mechanism mounted on said platform for arcuate movement about an approximately vertical axis, and means for operating said core-cutting mechanism including arcuate feeding movement thereof relatively to said 105 platform while the latter occupies a position adjacent such mine wall.

242. In a mining and loading machine, the combination with a main frame, of an elongated supplemental frame pivotally mounted on said main frame for up and down movement relatively thereto, dislodging mechanism mounted at the forward end of said supplemental frame, means for operating said dislodging mechanism including 110 arcuate feed thereof in a general horizontal direction across the mine wall in advance of said supplemental frame, and means for swinging said supplemental frame vertically to adjust the elevation of said dislodging mechanism on a comparatively long radius.

243. In a mining machine, the combination with a main frame, of an elongated supplemental frame pivotally mounted on said main frame for up and down movement relatively thereto, a conveyer extending longitudinally of said supplemental frame, core-cutting mechanism mounted on said supplemental frame at the end thereof opposite its pivotal connection with said main frame, 125 130

and means for operating said core-cutting mechanism including swinging feeding movement thereof relatively to said supplemental frame on an upright axis.

5 244. In a mining machine, the combination with cutting mechanism, of means for operating said cutting mechanism to dislodge from a mine wall comparatively large blocks of material, a material-moving device 10 for engaging the dislodged blocks of material and moving them from their native positions in the mine wall, and power transmission means for actuating said material-moving device.

15 245. In a mining and loading machine, the combination with a supporting frame, comprising a platform, of conveyer mechanism extending rearwardly from said platform, core-cutting mechanism mounted for 20 arcuate movement relatively to said platform, means for operating said core-cutting mechanism, means for moving the core from a mine wall along said platform to said conveyer mechanism, and guiding mechanism 25 for directing the core onto said conveyer mechanism.

246. In a mining and loading machine, the combination with a frame, of core-cutting mechanism mounted on said frame, 30 means for operating said cutting mechanism including arcuate feed thereof on an upright axis and in a general horizontal direction, a conveyer carried by said frame, and means for effecting the transfer to loading position 35 of material dislodged by said core-cutting mechanism.

247. In a mining machine, a loop cutter, means for rotating said cutter about an upright axis, an apron secured to said cutter 40 and movable therewith into the upright kerf formed thereby, and a reel for paying out said apron to permit the movement of said apron with said cutter.

248. In a mining and loading machine, 45 the combination with a supporting frame, of kerf-cutting mechanism mounted thereon, loading apparatus mounted on said supporting frame, a rope connected to said loading apparatus, means for exerting a pull on 50 said rope, and mechanism for guiding said rope to effect the feeding of said kerf-cutting mechanism when said rope pulling means is operated.

249. In a mining machine, the combination 55 with core-cutting mechanism, of a main frame, a supplemental frame movable relatively to said main frame and pivotally supporting said core-cutting mechanism, power mechanism mounted on the rear of 60 said main frame, and flexible power transmitting mechanism between said power mechanism and said core-cutting mechanism.

250. In a mining machine, the combination 65 with a cutter-head frame, comprising

upper and lower arms spaced from one another, of means for pivotally supporting said cutter-head, a cutter frame pivoted between said arms on an upright axis and having an unobstructed core-opening there-through, an endless chain cutter mounted on said cutter frame to travel about said unobstructed core-opening, means for driving said chain-cutter, and means comprising gearing for arcuately moving said cutter-frame to effect arcuate feeding movement of said chain-cutter while being driven.

70 251. In a mining machine, the combination with a supporting frame, of core-cutting mechanism mounted thereon and having an unobstructed core-opening there-through, and an ejector mounted on said frame for movement relatively thereto along a path substantially parallel to the path of said core-cutting mechanism in position to 75 act on the cut material to move the same from its position at the mine wall.

252. In a mining machine, the combination with a supporting frame, of core-cutting mechanism mounted on said frame and having an unobstructed core-opening there-through, an ejector mounted on said frame for movement relatively thereto in position to act on the core material to move the same from its position at the mine wall, and 90 means for operating said ejector by moving the same relatively to said supporting frame against the core material to move the latter from its position at the mine wall relatively to said supporting frame.

100 253. A mining machine comprising a supporting frame, cutting mechanism mounted on said frame for completely cutting a section of material from a mine wall, a follower mounted on said frame for movement relatively thereto, and means for operating said follower to cause the same to engage the cut-out body of material in the position assumed thereby after being cut, and forcing such cut material away from such position.

254. In a mining machine, the combination with a supporting frame, of core-cutting mechanism mounted thereon and having an unobstructed core-opening there-through, of means for operating said core-cutting mechanism, and an ejector in position on said frame to act on the cut material immediately after being cut and in the position assumed thereby after being cut, 115 said ejector being mounted on said frame in position to reach the cut material along substantially the entire mass thereof.

255. In a mining and loading machine, the combination with core-cutting mechanism, of conveyer mechanism, and means for receiving and directing the dislodged material from said cutting mechanism to said conveyer mechanism.

120 256. In a mining and loading machine, 130

- the combination with core-cutting mechanism, of conveyer apparatus, and a chute for directing dislodged material onto said conveyer apparatus.
- 5 257. In a mining machine, the combination with a supporting frame, of loop chain core-cutting mechanism mounted on said frame and having an unobstructed core-opening therethrough, means mounted on said frame for transferring cut material toward loading position, and means mounted on said frame in position to receive cuttings from said loop chain core-cutting mechanism and transfer such cuttings to 10 ward said loading position.
- 10 258. In a mining machine, the combination with a supporting frame comprising a platform, of core-cutting mechanism having an unobstructed core-opening therethrough 20 and mounted on said platform for swinging feeding movement on an upright axis, loading apparatus for transferring the cut core of material from the mine wall toward loading position, and a chain conveyer on said 25 platform traveling from a position adjacent the lower inner portion of said core-cutting mechanism for receiving the cuttings from the core-cutting mechanism during its arcuate feed about said upright axis, and 30 transferring such cuttings away from the mine wall.
259. In a mining machine, the combination with a supporting frame comprising a platform, of loop chain core-cutting mechanism mounted on said frame in an upright 35 plane, said core-cutting mechanism having a lower run extending above said platform to cause cuttings from said cutting mechanism to be deposited on said platform, and 40 a conveyer movable over said platform to gather the cuttings where deposited by said cutting mechanism and transfer such cuttings toward the rear portion of said supporting frame.
- 45 260. In a mining machine, the combination with a supporting frame comprising a platform, of core-cutting mechanism having an unobstructed core-opening therethrough and mounted on said frame in position 50 to cut a single core extending in a general horizontal direction through said unobstructed core-opening, said core-cutting mechanism being also mounted on said frame in position to deposit cuttings onto said 55 platform, and a conveyer mounted on said frame with flights moving over said platform in position to act on the cuttings deposited on said platform by said core-cutting mechanism and transfer such cuttings 60 away from the cutting mechanism.
- 55 261. In a mining machine, the combination with a frame comprising a bed plate, of a chain core-cutter mounted on said frame, a trough on said bed plate adjacent the emerging run of the chain cutter, and 65 a conveyer movable along said trough to transfer the cuttings received by said trough automatically from said chain cutter.
262. In a mining machine, the combination with a frame comprising a bed plate, 70 of a chain core-cutter arranged to discharge the cuttings formed thereby onto said bed plate, a conveyer in position on said bed plate to transfer toward loading position the cuttings from the positions where deposited by said core-cutter, and apparatus 75 for transferring the cut core material to said conveyer for transfer by the latter toward loading position.
263. In a mining machine, the combination with a receiving platform, of a supporting frame for carrying said receiving platform at the forward end thereof, an adjustable extension from the forward end 80 of said platform, and means for manually moving said extension relatively to said platform.
264. In a mining machine, the combination with a supporting frame comprising a base plate at the forward end thereof curved 90 to conform to the face of a mine vein in which an arcuate cut has been previously made, an extension beyond the forward curved end of said base plate, said extension being also curved to approximately conform 95 to said arcuate cut face, and manual means for adjusting said extension relative to said base plate to fill the gap between the forward end of said base plate and the curved face of said mine vein.
265. In a mining machine, the combination with a loop chain core-cutter having an unobstructed core-opening therethrough, of means for operating said core-cutter to sever a section of material from a mine vein by 105 forming a kerf therein, loading apparatus comprising a conveyer, a supporting frame for carrying said core-cutter and for guiding said conveyer in association with said core-cutter to automatically transfer the 110 cuttings directly from said core-cutter toward loading position, and means for controlling the operation of said loading apparatus at the will of the operator.
266. The combination with a mining machine, of frame-work comprising spaced-apart arms pivoted to said mining machine on opposite sides thereof, a pair of roof jacks for holding said framework in stationary position while providing a free and 120 unobstructed space for up and down tilting movement of said mining machine, and mechanism connected between said mining machine and said arms for tilting said mining machine on its pivotal connections to 125 said arms.
267. In a mining and loading machine, the combination with a chain-cutter, of means for operating said chain-cutter to sever a section of material from a mine vein 130

by forming a kerf in said material, a conveyer, means for supporting said chain cutter in such position as to cause the same to discharge its cuttings into the path of movement of said conveyer, means for moving the material severed by said chain-cutter into position to be transferred by said conveyer toward loading position, and means for controlling the movement of said conveyer at the will of the operator.

268. In a mining machine, means for forming a kerf in a mine vein, a platform conforming to the contour of the unmined mass for receiving material as it is severed from its native position, and an apron arranged to be moved into the kerf formed by said kerf-forming means.

269. In a mining machine, a frame comprising a lateral bed plate, a conveyer having flights movable over the surface of said bed plate, an upright chain core-cutter arranged to discharge the cuttings formed thereby onto the forward end of said bed plate, and a rib extending upwardly from said bed plate adjacent the path of movement of said flights and the forward end of said conveyer to prevent escape of the cuttings formed by said core-cutter out of the path of movement of said flights.

270. In a mining machine, the combination with a supporting frame, of a receiving structure mounted thereon, core-cutting mechanism mounted at one end of said receiving structure, means for guiding said core-cutting mechanism along a path of travel inclosing a space in alinement with said receiving structure, and means for operating said core-cutting mechanism including the feed thereof along such path of travel to cut a core of material in one feeding operation in a mine wall in alinement with said receiving structure.

271. In a mining machine, the combination with a supporting frame, of a receiving structure mounted thereon, core-cutting mechanism, means for guiding said core-cutting mechanism back and forth in approximate alinement with said receiving structure, means for operating said core-cutting mechanism to cut in one operation a core of material in a mine wall in alinement with said receiving structure, and means for bodily moving said core-cutting mechanism relatively to said receiving structure in a direction opposite to the feeding direction.

272. In a mining machine, the combination with a supporting frame, of a chain-cutter comprising an upright frame mounted on said supporting frame, means for driving said chain-cutter with its lower run traveling toward said supporting frame after emerging from the mine wall adjacent said supporting frame, and a conveyer mounted on said supporting frame adjacent the lower run of said chain-cutter in posi-

tion for removing the cuttings delivered to it by the said lower run.

273. In a mining machine, the combination with a supporting frame, of a chain-cutter comprising a frame and a chain traveling about the periphery thereof in an upright plane, means for driving said chain-cutter in an upright plane with the lower run emerging from the mine wall to deliver cuttings to the said supporting frame adjacent said lower run, and a conveyer on said supporting frame with its path of travel adjacent the various positions of the lower run of said chain-cutter where it emerges from the mine wall.

274. In a mining machine, the combination with a supporting frame, of a loop chain core-cutter having an unobstructed core-opening extending laterally therethrough, means for driving said chain-cutter, means for swinging said cutter about an upright axis to feed the said cutter relatively to said supporting frame, and a flight conveyer mounted on said supporting frame in position to travel along an arcuate path in a generally horizontal plane to receive the cuttings from said cutter as the latter is swung in its feeding movement about said upright axis.

275. In a mining machine, the combination with a supporting frame comprising a platform, of a conveyer operable approximately in the plane of said platform, kerf-cutting mechanism mounted on said supporting frame in a position entirely separated from said conveyer, means for operating said kerf-cutting mechanism including driving thereof by causing the lower portion thereof to emerge from the mine wall above the forward portion of said platform onto said conveyer, and means for driving said conveyer to remove the cuttings received thereby from said separate kerf-cutting mechanism.

276. In a mining machine, the combination with a supporting frame, of kerf-cutting mechanism mounted near one end of said supporting frame in an upright plane and to swing laterally on an upright axis, means for swinging said kerf-cutting mechanism about such upright axis, means for driving said kerf-cutting mechanism, and a conveyer on said supporting frame in position to receive cuttings from said kerf-cutting mechanism while operating during the swinging feeding movement thereof.

277. In a mining machine, the combination with a supporting frame comprising a platform, of dislodging mechanism mounted on said frame for operation at a mine wall above said platform, and an adjustable extension on said platform adapted to be moved relatively to said platform to abut against the mine wall to close the gap be-

tween the forward end of said platform and said mine wall.

278. In a mining machine, the combination with a swinging frame having an unobstructed core-opening therethrough, of cutting mechanism mounted on said frame, means for operating said cutting mechanism including the swinging of said frame to cut an arcuate core in a mine wall, and a flexible draft device acting on the outer end of said frame to swing the same back toward initial position.

279. In a mining machine, a loop chain-cutter, means for swinging said cutter about an upright axis, a base plate over which said cutter moves, a conveyer arranged to travel over said base plate and having horizontal

extending flights secured thereto, the path of said conveyer being arranged adjacent the path of the end of the return run of said cutter as said cutter moves about its axis, and a ridge formed on said base plate extending around the periphery of the path of travel of said conveyer to prevent escape of material from said conveyer.

In testimony whereof I have signed my name to this specification, in the presence of two subscribing witnesses, on this 30th day of June, A. D. 1914.

EDMUND C. MORGAN.
